TELEPHONE SYSTEM

John H. Voss, Downers Grove, Ill., assignor to
 Associated Electric Laboratories, Inc., Chicago,
 Ill., a corporation of Delaware

Application March 24, 1937, Serial No. 132,687

45 Claims. (Cl. 179—27)

The present invention relates to telephone systems and more particularly to improvements in private branch exchange systems of the type having access over trunk lines to the lines of one or 5 more central exchanges.

There are numerous well-known types of private branch exchanges of different designs such that one or more thereof is capable of meeting the service requirements of practically any business requiring such a system. In the larger systems of this type automatic equipment or local switch trains, comprising the usual traffic concentration switches and connector switches conventionally employed in larger public systems, is 10 almost universally used for setting up desired connections between the various party lines included in the exchange. For the extension of connections from the private exchange lines to the central exchange, however, a number of different methods have been devised. One of the best arrangements yet developed for this particular purpose is that of providing, in the branch exchange, automatic equipment in the form of connector or selector switches associated with two-way 15 trunk lines extending between the private and central exchanges and responsive to the operation of any one of the private exchange line substation impulsion means, for setting up connections directly to the equipment of the central exchange, whereby talking loops from the private exchange lines to lines terminating in the central exchange may be established, and in routing incoming calls to the lines of the private exchange through apparatus associated with an attendant's cabinet or operator's station in such 20 manner that the necessary connections are set up by the operator, following which the desired connections between the calling and called lines are completed. This arrangement possesses many 25 advantages with respect to flexibility in the types of service available and also may easily be adapted successfully to operate in connection with any type of central exchange equipment.

The principal disadvantage of known systems 30 of the form just described relates to the complexity of the circuits involved and the arrangement thereof, which arrangement inherently contributes to or causes mistakes on the part of the operator at the attendant's cabinet. Thus, various 35 types of service such, for example, as the completion of calls to private exchange lines, the monitoring of established connections, the holding of calls, and the like, are usually required with this type of system, and each of these various 40 services requires one or more operations on the

part of the operator in the form of the manipulation of operator controlled key switches. Consequently, where a large volume of traffic is being handled, there is great likelihood of mistakes tending to interfere with correct service. The 5 more serious of these errors are brought about by the operator failing to manipulate keys at the proper time, thus, in many cases, leaving central office trunk line equipment tied up when it is actually idle. The last-mentioned errors are 10 traceable directly to the fact that key switches of the self-locking type are necessarily used in all of the prior systems of this character, which switches complete directly the necessary connections for the particular service to be rendered, 15 and these switches, when not manipulated at the proper time during a particular operation, may put the associated repeater and trunk circuits temporarily out of use.

It is an object of the present invention, therefore, to provide a system of the character briefly described which operates in a manner such that the operations required for rendering the various types of services are extremely simple and are capable of being performed mechanically with 20 but little thought on the part of the operator.

It is another object of the invention to provide such a system wherein, for particular types of service, only momentary operation of non-locking operator controlled switches is required to 25 cause the necessary connections to be established.

It is a further and more specific object of the invention to provide an arrangement of the above character wherein, at the end of the manipulation or sequence of manipulations of the 30 operator controlled switches, necessary to render a predetermined service, and when the operator's telephone is disconnected from all lines, the switches are all in their respective normal positions.

It is a further object of the invention to provide a system of the character stated which is operable to provide practically any type of service required and possesses the utmost simplicity with respect to circuit arrangement and the type 45 of equipment included therein.

In general, the objects as set forth above are attained in accordance with the present invention by providing in a system of the form described, an operator's station or attendant's cabinet associated with the incoming central office trunk line and repeater circuits and having its operator controlled key switches so related to the control equipment associated with the individual trunk line repeaters that only the initia- 50 55

tion of connections for the various required services is performed by the operator controlled key switches, the actual setting up of the necessary connections being carried out by means in the 5 form of relays responsive to the operation of the key switches to predetermined positions. More particularly, one or more relays are provided, each of which is so connected as to be energized or deenergized by the momentary operation of one or more of the associated key switches, following which it initiates an operation, or a sequence of operations, ultimately resulting in the appropriate connections for a particular desired service. When the service is no 10 longer desired or when the particular repeater being used is cleared out by disconnecting an established connection, these relays and the other equipment controlled thereby are automatically restored to normal. Wherever possible self-restoring key switches are used in association with 15 each of these relays, thereby eliminating the possibility of key switches being left locked in a position which will interfere with the subsequent use of the associated repeater and central office 20 trunk line. The circuit arrangement of the switches and the relays controlled thereby is such that, when all of the keys normally used by the operator in performing routine services are in their respective normal positions, the operator's 25 telephone is disconnected from all lines. More specifically, the arrangement is such that the operator's telephone cannot be disconnected from all of the lines unless the keys are in their normal positions, thus providing a safeguard against 30 mistakes due to lack of thought on the part of the operator.

The novel features believed to be characteristic 35 of the invention are set forth with particularity in the appended claims. The invention, however, both as to its organization and method of 40 operation, together with further objects and advantages thereof, will best be understood by reference to the specification taken in connection with the accompanying drawings in which Figure 1 illustrates diagrammatically a system of 45 the general type described above and Figs. 2, 3, and 4, considered together, illustrate the apparatus and improved arrangement of the circuits included in the operator's station and the associated 50 trunk line circuits.

Referring now more particularly to Figure 1 of the drawings, there is diagrammatically illustrated a one thousand line system of the general form described above which includes a central office or exchange 10 connected by one or more two-way trunk lines, such as the line 11, to a private exchange. The latter exchange comprises two-way trunk repeater circuits, one of which is shown schematically at 12, which circuits 55 are individually associated with the trunk lines such as the line 11, to which line are accessible the apparatus of an operator's station or attendant's cabinet 13 and also at least a portion of the private lines included in the private exchange. 60 The latter lines, three of which are shown at 14, 15 and 16, extend between the subscribers' stations, as shown at A, B and C, respectively, and line switches included in the line switch unit 17 and are multiplied to connector switches, one 65 of which is indicated at 18. Each of the connector switches is preferably of the well-known Strowger type comprising bank contacts arranged in levels, wipers, and control means arranged to translate the wipers vertically opposite any desired level in response to the dialing of one digit

and then to rotate the same into engagement with the correct set of contacts in response to the dialing of a second digit. The line switches included in the units 17 and individually associated with each of the private lines likewise may 5 be of any desired type although preferably they are of the plunger or rotary type having their bank contacts multiplied together in groups and connected over trunk lines such as that indicated at 19 to selector switches one of which is indicated at 20, individually associated with the lines 10 19. The selector switches may also be of any desired form although, preferably, they are of the well-known Strowger type comprising bank contacts arranged in levels and multiplied in 15 groups to different groups of lines corresponding to the groups of selector bank contact multiples, each group comprising individual lines such as that shown at 21, extending from each selector switch bank contact multiple to the connector 20 switches, such as the switch 18. The selector switches of the form noted also comprise wipers adapted to be translated vertically to the proper level of bank contacts in response to received impulses transmitted thereto by the dialing device 25 of a calling substation, following which they are automatically rotated into contact with the first idle line such as the line 21. One group of selector switches has at least a portion of its bank contacts connected over trunk lines as indicated 30 at 22 to the repeaters, such as the repeater 12, associated with the trunk lines, such as the line 11 extending to the central exchange. With this arrangement, a party on a private exchange line may, in a well-known manner, by dialing a pre-determined digit cause a connection to be established directly over one of the central office trunk lines, such as 11 to the central exchange. An additional, or the same group of selector switches 40 may, if desired, have one or more contact multiples extended directly over lines, such as the line 31, to the operator's station 13 to provide secretarial or executive service for at least a portion of the private lines in the private exchange in the manner more particularly described hereinafter. In order to render the subscribers' lines 45 accessible to the central exchange trunk lines such as the line 11 on incoming calls from the central exchange 10, line switches are individually provided for each of these trunk lines, one of which is shown at 33', which switches have 50 their bank contacts multiplied together and extended over lines, such as the line 24, to certain of the selector switches. If desired, individual selector switches may be employed to connect the lines extending from the multiplied bank contacts of the line switches, such as the switch 33', to the connector switches but, preferably, certain of the selector switches, such as the switch 20 included in the switch train between the subscribers' lines and the connector switches, are used for this purpose. In order to enable the operator directly to call any desired private exchange line in the private exchange without using 60 one of the central exchange trunk lines, there are provided means in the attendant's cabinet for connecting the operator's telephone to the private exchange local switch train over a line 65 32, a line switch 33 and lines such as the line 34 extending to one or more of the selector switches. 70 Information trunk lines, such as that shown at 31, may also be provided for use in rendering secretarial or executive service to all or certain designated ones of the private exchange lines in the manner described in detail hereinafter. In 75

addition, the usual provisions are made for night service, whereby incoming calls to the private exchange are routed directly to night attendants' telephones included in the private exchange.

- 5 Neglecting for the present the details of the operator's station or attendant's cabinet 13 and the associated central exchange trunk lines and repeaters, the system as generally described above is entirely conventional in form and its operation 10 is well understood in the art. In brief, calls between private lines within the private exchange and calls from private lines to the central office are completed independently of the attendant's cabinet and the apparatus included therein, this 15 apparatus being used primarily in the extension of calls originating on lines terminating at the central exchange to lines in the private exchange and in providing the various types of service described hereinafter. Thus, the initiation of a 20 call on the line 14 causes the line switch included in the unit 17 associated with this line to select an idle trunk line such as the line 19 leading to an idle selector switch such as the switch 20. The latter switch, in response to the 25 dialing of the first digit at the station A, selects the group of trunk lines associated with the connector switches at which the called line terminates and thereafter automatically selects an idle one of this group of trunk lines to extend the 30 connection to the associated idle connector switch. In response to the dialing of the final two digits, the selected connector switch extends the connection to the desired called line or, in case the called line is busy, returns busy tone to the calling 35 party.

- In the event a call is to be extended from one of the lines in the private exchange to a line terminating at the central exchange, the operation is exactly the same as that described above except that the call is routed in response to the 40 dialing of one predetermined digit, such as 0, by means of one of the selector switches over one of the lines such as the line 22 to a trunk line such as the line 11 extending to the central exchange 10. If the apparatus included in the latter exchange is automatic, the connection as thus extended to this exchange may further be extended to the called subscriber's line by dialing the proper additional digits. If, on the other hand, the exchange 10 is manual in character, 45 the extension of a call thereto from one of the lines in the private exchange notifies the central exchange operator by suitable signal means, who thereafter in a well-known manner extends the connection to the desired central exchange line. As described in detail hereinafter, the extension 50 of a connection from a line in the private exchange to a line in the central exchange is entirely independent of any operation on the part of the operator at the attendant's cabinet 13. On incoming calls from the central exchange, the operator at the operator's station 13 is first 55 signaled that a particular central exchange trunk line is calling in, whereupon she operates one of the key switches at the station to connect her telephone to the calling trunk line and establish a talking loop extending over the trunk line from her telephone to the central exchange. The operation of the key switch mentioned also prepares a normally uncompleted talking loop from 60 the operator's telephone to the called private exchange line by causing the associated line switch, such as the switch 33', to seize an idle selector switch, such as the switch 20. Following 65 receipt of the information as to the party in the

private exchange desired by the calling party, the operator momentarily operates a second key to interrupt the established talking loop to the central exchange and to connect her telephone to the prepared loop to the called private line. 5 In response to the operator's dialing of the first digit, this loop is extended by means of a line switch such as the switch 33', an idle line such as the line 24 and an associated first selector switch such as the switch 20 over an idle line 10 such as the line 21 to the associated connector switch, following which the talking loop between the operator's telephone and the called line is completed by dialing the proper final two digits at the operator's station 13. If the called party 15 answers, the connection between the calling and called party may be completed and the disconnection of the operator's telephone from the established connection may simultaneously be accomplished by the restoration of the first operated key switch to its normal position. Hence, the operator's equipment is released for use in completing other calls of a similar nature. Suitable provisions are also made for monitoring any desired established connection, for splitting the 20 connection so that the operator can talk with either the called or calling party to the exclusion of the other, for holding an incoming call until a desired line in the private exchange is 25 clear and for providing all of the other services 30 normally required in this type of exchange.

It is pointed out that each of the lines such as 22 and 35 extending respectively to and from the associated repeater, such as the repeater 12, 35 are of the three conductor type and that the central exchange trunk lines, such as the line 11, are of the two conductor variety. Thus, the line 22 comprises two talking conductors 28 and 29 and a control conductor 30, the line 35 comprises a pair of talking conductors 25 and 27 and a control conductor 26, and the trunk line 11 comprises a pair of talking conductors 23 and 24. From the foregoing general description it will be appreciated that each of the trunk lines, such as the line 11, comprises a portion of an 40 uncompleted talking loop extending between the operator's telephone and the central exchange; that each of the lines 35 comprises a part of a normally uncompleted talking loop extending from the operator's telephone to any desired line 45 50 in the private exchange, and that when these two loops are connected together an extended talking loop is completed between the calling and called telephones. It will further be appreciated that the local switch train of the private 55 exchange, comprising the line switches such as the switch 33', the selector switches such as the switch 20 and the connector switches such as the switch 18, is associated with the normally uncompleted loop extending between the operator's 60 telephone and each of the private exchange lines and that this switch train is arranged to be responsive to operation of the impulsing or dialing device at the operator's station. 65

Referring now to Figs. 2, 3, and 4, there are illustrated the features of the present invention as embodied in the apparatus for setting up, in the above described manner, connections between the private exchange lines included in the private exchange and the lines extending to the central exchange 10, and more particularly as embodied in the circuits and apparatus of the repeater 12 associated with the central office trunk line 11, the circuits and apparatus of the operator's sta- 75

tion or attendant's cabinet 13 and the connections between the various elements of these two portions of the system. It is pointed out here that the various relays involved are, for convenience in following the description, related to the number of the figure in which they appear, being numbered consecutively in steps of ten with the intervening numbers designating the armatures of the corresponding relays. In brief, the portions of the system shown in detail in Figs. 2 and 3 comprise; a normally interrupted talking loop extending from the operator's station to the central exchange and including the repeater windings 204 and 205 of a repeater 200 connected in series with each other across the trunk line conductors 23 and 24 through the voice current coupling condenser 206 and a resistor 207; a normally uncompleted outgoing private exchange talking loop including the repeater windings 201 and 202 connected in series by means of a condenser 203 across the line conductors 214 and 215 and terminating at the banks of one of the selector switches such as 20; a normally uncompleted talking loop extending from the operator's telephone to any one of the private exchange lines by way of the conductors 228 and 229, the conductors 274 and 275, the conductors 25 and 27 and the line switch 33'; a normally uncompleted talking loop between the central exchange and any one of the private exchange lines comprising elements of the first and third loops as described above and the conductors 276 and 277; and means comprising different groups of the plurality of relays shown and their control and controlled circuits for setting up either alone or in cooperation with certain elements of the equipment in the attendant's cabinet the variety of connections necessary to a rendition of the various required services. Thus, there is provided means included in the repeater circuit and operative to set up a connection from a private line by way of the trunk line 11 to the central exchange, which means comprises relays 210, 310 and 320 operative in the order named during such an operation, the conductors included in the circuits controlling these relays and the conductors included in the circuits controlled thereby. Similarly, there is provided means included in this portion of the system for setting up connections to a desired private line on a call from the central exchange, which means comprises, in addition to an operator controlled trunk line answer and release key switch 425, a switch 426 and an impulsing device 458 at the operator's station 13, relays 330, 340, 350, 360, 230, and 370, operative in the order named during the initiation of such a connection, and relays 250, 210, 310, 320, and 260, which also operate in the order named, to complete the connection following the appropriate manipulation of the switch 425 and 426 and the impulsing device 458. In addition, there is provided a condenser 218 which is connected in series with the two halves of the line 229 for a purpose to be described hereinafter, and various other circuit elements and conductors which are specifically referred to hereinafter.

The apparatus at the operator's station shown in Fig. 4 comprises, in addition to a plurality of operator controlled switches 425, one for each of the central office trunk lines such as 11, a night switch 424, an operator controlled local release and monitoring key switch 427, an operator controlled trunk connect and local key switch 426, a night alarm key switch 470, an information key switch 482, an operator's line key switch 483, suit-

able indicating lamps 400, 401, 484, and 410, and an operator's telephone indicated generally at 500 and including all of the apparatus to the left of the terminals 465 and 466. This telephone is accessible and may be connected to the trunk line 11 by means comprising the conductors 228 and 229. It will be understood that these conductors are multiplied to armatures of additional relays such as the relay 250 individually associated with corresponding ones of other central exchange trunk lines, thereby to make the operator's telephone accessible to any one of these trunk lines. In this connection it is pointed out that switches such as the switches 424, 425, and 470 are individually provided for each trunk line and that the remaining switches are common to the operator's equipment, only one of each being required for the telephone 500. In addition, there is included at the operator's station conductors interconnecting the contacts of the various switches, some of which extend to the control means associated with the trunk 11 and all suitably identified by reference characters to facilitate a description of the operation of the apparatus.

Each of the operator controlled switches 425, 426 and 427 may be of any desired commercial construction and comprises, in addition to the contact springs shown, a suitable camming element for operating the contact springs. Each switch has a normal position, corresponding to the unbiased positions of the contact springs as illustrated in the drawings, and at least one off-normal position wherein the right or left-hand contact springs are biased into or out of engagement with their associated contacts. In addition, each of the switches is, so far as possible, constructed to be of the non-locking type such that, when released from an off-normal position, it automatically restores to its normal position. Thus, the switch 425 automatically restores from its trunk release or right-hand off-normal position and is locked when operated to its answer or left-hand off-normal position, the switch 426 automatically restores to normal when released from either of its two off-normal positions, and the switch 427 locks itself in an off-normal position only when its camming element is moved to the left. The practicability of employing, wherever possible, self-restoring key switches results from the arrangement of the circuit elements in accordance with the present invention. It will be appreciated that by using such key switches mistakes on the part of the operator are minimized.

The operator's telephone or substation 500 may be of any desired type, although, preferably, is of the well-known anti-side tone, booster type, of which there are several well-known modifications in the art. It comprises an operator's hand set including a receiver 459 and a transmitter 460 adapted to be connected in circuit for operation by the hook switch comprising associated pairs of contacts 461 and 462. Thus, when the hand set is lifted from the hook switch, the receiver terminals extend by way of the contacts 462 and a condenser 467 to opposite terminals of a winding 448 embodied in a three winding induction coil 450, the terminals of the receiver being shunted by a rectifier 468, preferably of the copper oxide type, which functions to prevent current surges through the receiver during dialing and thereby to prevent receiver clicks. Connected in series with the winding 448 across the line conductors 445 and 446 by way of contacts in the impulsing

device 458, the switches 426 and 427 and the hook switch is a second winding 447. Inductively coupled to these two windings is the third winding 449 of the coil having its terminals extending 5 to the terminals of the transmitter 460. Current is supplied to the transmitter 460 from common battery through two resistive inductors indicated at 464, the series combination of these inductors and the common battery being by-passed for 10 audio frequency currents by a condenser 463. The impulsive device conventionally comprises impulse contact springs 452 and 453 shunted by an anti-contact-sparking circuit comprising a resistor 480 and a condenser 481, and contact 15 springs 454, 455 and 456, 467 for shunting the receiver 459 and the induction coil windings 447 and 448 during a dialing or impulsive operation. Since the operation of this type of substation circuit is well known in the art, a detailed explanation 20 is deemed to be unnecessary and is omitted in the interests of simplicity.

The above described control apparatus at the operator's station in conjunction with the control means associated with the trunk line 11 is 25 capable, when properly operated, of providing in an improved manner practically all of the services usually required in the type of system shown. Thus, in the operation of the repeater circuit to extend a connection from one of the lines in the 30 private exchange to the central exchange and following the seizure, at the selector switch 20, of the trunk 11 and its associated repeater 12 in the manner previously described, the windings of the relay 210 are energized over a circuit extending 35 from ground at the lower winding of the relay 210, through this winding, the armature 248 of the relay 240, the conductor 208, the winding 202 of the repeater 200, the line conductor 215, the armature 231 of relay 230, the trunk line conductor 40 28, over the closed bridge across the conductors 28 and 29, the trunk line conductor 29, the armature 232 of relay 230, the line conductor 214, the repeating coil winding 201, the conductor 209, the armature 247 of relay 240 and through the 45 upper winding of relay 210 to battery. The relay 210 operates to complete at its armature 211 a circuit including the conductor 347 for energizing the upper winding of the relay 250 and the relay 310, and also to close at its armature 212 ground 50 from the armature 323 of relay 320 to the negative trunk line conductor 24 over a path including the winding 204 of the repeater 200, the resistor 207 and the winding 205 of the repeater 200. The relay 210 also closes its armature 213 55 to the associated contact, but this operation is without effect since the conductor 216, to which the armature 213 is connected, is held from ground at the armature 257 of relay 250.

The energization of the upper winding of the 60 relay 250 is insufficient to cause operation thereof, this relay operating only when both its windings are cumulatively energized. The effect of closing ground to the negative trunk line conductor 24 at the armature 212 is to operate equipment in the central office, the nature of the 65 operation depending upon the type of equipment employed therein, i. e., whether automatic or manual, as will be pointed out hereinafter. In either case ground is returned over the positive 70 trunk line conductor 23 so that when the relay 310 operates it completes at 315 an obvious energizing circuit for the upper winding of relay 320 and prepares at its armature 311 a holding circuit for this relay including the lower winding 75 thereof. In addition, the relay 310 closes at its

armature 314 ground to the control or C conductor 218 which extends back through the contact 219 and armature 226 of the test busy switch to the bank contacts of the connector switch or switches to prevent the repeater 12 and associated trunk line 11 from being seized thereat until the trunk line is released. The relay 310 at its armature 312 also closes ground to the motor start or ringing machine conductor 227, thereby to initiate operation of the ringing apparatus (not shown), and opens at its armature 313 the energizing circuit of the relay 339 normally bridged across the line conductors 23 and 24.

The application of ground to the C conductor 15 218 in the manner described above, in addition to marking the trunk line 11 as busy, causes the busy lamp 400 included in the attendant's cabinet to be lighted over a circuit extending from ground over the conductor 218, through the 20 contact 219 and armature 226 of the busy switch, the conductor 413, the armature 417, and contact 418 of the night switch 424, and through the lamp 400 to battery. The lighting of this one lamp indicates to the operator that the repeater and associated trunk line 11 are in use by a party in the private exchange calling through to the central exchange.

The relay 320 is of the well-known two-step type such that when its upper winding is energized in the above described manner its X contacts only are closed at the armature 324. The closure of these contacts completes the previously prepared circuit for the lower winding of the relay by way of the armature 311, thereby 35 resulting in its complete operation to complete, at its armature 322, a talking loop extending from the calling line to the central exchange and in the closure, at its armature 321, of a multiple ground to the C conductor 218. Operation of the 40 armature 322 also disconnects ground from the negative line conductor 24 at the armature 323, to interrupt the circuit of the upper winding of relay 320, this relay remaining operated, however, by virtue of the energization of its lower 45 winding as described above.

At this point in the operation, the connection has been extended from the calling line to the central exchange and, as was mentioned previously, the steps following those described above necessary to a completion of the desired connection are dependent upon the type of equipment embodied in the central exchange. If this equipment is automatic in character, dial tone will be returned over the talking line conductors following the operation of the relay 320 50 indicating to the calling party that he may proceed to dial the desired line terminating in the central exchange. Operation of the dialing mechanism at the calling party's substation causes the line relay 210 to restore during each 55 impulse of each digit, thereby opening the central office loop circuit at the armature 212 and causing the operation of a train of automatic switches such as selector and connector switches, whereby the called subscriber's line is selected 60 and signaled in the usual manner. The relays 310 and 320, due to their slow release characteristics, remain operated during the impulse transmission so that when the relay 210 energizes at 65 the end of the final digit the talking loop is completed. Following the dialing, ringing current is supplied to the called subscriber's line at the connector in use in the central exchange, this 70 current being interrupted in the conventional 75

manner, when the called party answers, by the operation of a ring cut-off relay.

From the foregoing description it will be apparent that in those systems wherein the central exchange includes automatic equipment associated with the trunk lines such as the line 11, there is no necessity for applying ringing current to the conductors 23 and 24, since it serves no useful purpose. In the event manual equipment is employed, however, the ringing apparatus at the branch exchange may be used to apply ringing current to one of the line conductors 23 or 24 following the operation of the relay 320, to operate a signal at the central exchange, thereby to inform the operator in attendance to the trunk lines that a call is awaiting attention on the trunk line 11. Alternatively, the signal means may be operated when ground is closed to the negative trunk line conductor at the armature 212 of relay 210, as described above. When the operator answers the call, to receive the information necessary to a completion of the connection, the ringing current may be removed from the line conductor upon which it is impressed by any one of the several methods well known in the art.

Following the completion of the connection by either of the two methods described above, a talking loop is established between the calling and called lines which includes the trunk conductors 28 and 29, the armatures 231 and 232 of relay 230, the conductors 214 and 215, the repeater 200, the armature 212 of relay 210, the armatures 322 and 323 of relay 320 and the conductors 23 and 24 comprising the trunk line 11 leading to the central exchange. It is pointed out here that only three relays and their interconnecting circuits are involved in setting up the connection through the repeater, namely the relays 210, 310 and 320. These relays remain operated until the connection is cleared out.

Monitoring

With the system in this condition, the operator at the attendant's cabinet is aware that a connection has been established over the trunk line 11 due to the lighted condition of the busy lamp 400 and may monitor the call if desired by operating the trunk answer key 425 to the answer position to complete a circuit for operating the relay 220. This circuit extends from ground at the armature 431 of the trunk connect key 426 by way of the contact 432, the conductor 444, the contact 428 and the spring armature 402 of the switch 425, the conductor 404 and through the winding of relay 220 to battery. In response to the operation of the relay 220 the conductors 228 and 229 are respectively connected to the loop conductors 215 and 214 at the armatures 222 and 221, respectively. The connection of conductors 228 and 229 to opposite sides of the established talking loop extends the connection into the attendant's cabinet and terminates the same at the terminals 465 and 466 of the operator's telephone 500. Thus, the conductor 228 extends directly to the upper terminal 466, and the conductor 229 extends to the lower terminal 465 by a path including the armature 437 and contact 438 of the switch 427, the armature 441 and contact 442 of the switch 427, and the armature 434 and contact 433 of the switch 426, the terminal 465 being connected to the spring 453 and contact 452 of the impulsing device 458. As described previously, the potential across the 75 lower winding 448 of the induction coil 450 is

connected to the receiver 459 by way of the condenser 467 and the contacts 462 of the hook switch.

It may occur that the operator at the attendant's cabinet will cut in to monitor a call before the connections for the call are fully established since the busy lamp 400 is lighted immediately upon operation of the relay 320. In order to prevent such action from interfering with the completion of the connections, there is provided in the conductor 229 a condenser 485 in shunt with the contact springs 441 and 442 of the switch 427, which switch interrupts, when it is locked in its left-hand position, the direct current path through the induction coil windings 447 and 448. 15 Thus, the operator, in order properly to monitor a call, should first operate the switch 427 to its left-hand locking position to cut the condenser 485 into the circuit extending to the operator's substation 500 and then operate the answer key 20 switch 425 to its answer position to cause the operation of the relay 220 in the manner described above.

It will be noted that once the operator has cut in on an established connection to monitor a 25 call the only way in which the apparatus can be released from the connection for further use is to restore the answer key 425 to its normal position, thereby to open the energizing circuit of the relay 220. As will be pointed out hereinafter, not only is it possible to monitor a connection in the manner described above, but it is also possible to perform various other services such, for example, as the splitting of an established connection and the subsequent release of 35 the equipment for use in the completion of emergency calls.

Release

The manner in which the established connection is released at the conclusion of the conversation held over the trunk line 11 depends upon the nature of the equipment at the central exchange. If this equipment is automatic and when the party on the calling private line hangs up, the bridge across the talking conductors of 45 the private exchange loop is removed, thereby interrupting the previously traced energizing circuit of the relay 210 and permitting it to restore to open at its armature 212 the central exchange talking loop and at its armature 211 50 the energizing circuit of the relay 310. The slow-to-release relay 310 restores after an interval opening: at its armature 311 the holding circuit for the slow-to-release relay 320, at its armature 312 the connection to the ringing machine start conductor 227, at its armature 314 the ground connection to the C conductor 218, and closing at its armature 313 the winding of 55 the relay 330 across the line conductors 23 and 24. Since the line relay equipment in the central exchange will normally, in response to the opening of the central exchange talking loop at the armature 212, remove battery from the conductors 23 and 24 before the slow-to-release relay 310 restores, the closure of armature 313 to 60 the line conductor 24 does not result in the energization of the relay 330. Shortly thereafter the slow-to-release relay 320 restores, removing at its armature 321 the remaining ground connection to the C conductor 218, thereby marking the trunk line 11 as idle at the connector switch back contacts and extinguishing the busy lamp 400. At its armatures 322 and 323 the relay 320 prepares its initial energizing circuit and returns ground to the line conductor ex- 75

tending to the armature 212 of the relay 210, and at its X contacts open a further point in its holding circuit. The equipment is now in its normal or idle condition.

- 5 If, on the other hand, the central exchange equipment is manual in character, the trunk is held against seizure in the private exchange until the connection is cleared out at the central exchange, thereby guarding against a false routing 10 of a subsequent call due to the seizure of the line before the prior connection is fully released. Thus, and with such equipment, battery is present across the line conductors 23 and 24 until the line is cleared at the central exchange, so that, 15 when the relay 310 restores and before the slow-to-release relay 320 restores, the relay 330 is connected across the line at the armature 313 of relay 310, and, at its armature 331, closes an obvious energizing circuit for the relay 340. The 20 latter relay immediately operates to close at its armature 341 ground to the holding circuit of the relay 320. These operations occur before the relay 320 releases so that this relay is held operated to maintain at its armature 321 ground on the C conductor 218, thereby to identify the 25 trunk as busy at the connector bank contacts and to maintain the busy lamp 400 lighted. When the central station operator clears the line 11 at the central exchange, battery is removed from 30 across the line conductors 23 and 24, and the relays 330, and 340 restore, in the order named, to interrupt the holding circuit of the relay 320, whereupon the apparatus is restored to normal in the manner described above.
- 35 *Calls from the central exchange to the branch exchange*

On an incoming call from a line in the central office to a private line in the private exchange 40 and following the seizure of the trunk line 11, battery is extended over the line conductors 23 and 24 to energize and cause the operation of the relay 330. This relay operates and at its armature 331 closes the energizing circuit of the relay 340. The relay 340 operates and, at its armature 45 341 prepares a holding circuit for the relay 320, at its armature 342 prepares a holding circuit for itself, at its armature 344 applies guarding ground to the C conductor 218, at its armature 345 closes an obvious energizing circuit for the relay 350, and 50 at its armature 346 prepares a holding circuit for the slow-to-operate relay 370.

The relay 350 operates to close a holding circuit for itself at its armature 353 extending to ground at the armature 331 of the relay 330. This relay also closes ground to the ringing machine start conductor 227 at its armature 351, completes, at its armature 352, a circuit for the lower winding of the relay 320, completes, at its armature 354, the branch circuit across the conductors 23 and 24 including the winding of the alternating current relay 360 and the condenser 228, and prepares, at its armature 355, an energizing circuit for the winding of relay 240 by way of the conductors 217 and 236.

In response to the energization of its lower winding at the armature 352, the relay 320 operates to close multiple ground to its lower winding by way of the armatures 324 and 341. In addition, this relay extends, at its armature 322, the line conductor 23 to the armature 212 of the relay 210, closes multiple ground to the C conductor 218 at its armature 321 and removes ground from the positive line conductor 23 at its armature 70 323. Ringing current is now applied, in the usual

manner, to the line conductors 23 and 24 at the central exchange, thereby causing the energization and operation of the alternating current relay 360. This relay at its armature 361 completes, by way of the conductor 231, the energizing circuit for the relay 230. The latter relay at its armatures 231 and 232 connects direct generator to the line conductors 28 and 29 but without effect at this time, this current being effective only when the attendant's cabinet apparatus is 10 set to switch incoming calls by way of the line conductors 264 and 265 to the night telephone in the manner to be described hereinafter. At its armature 234 the relay 230 connects over the conductor 238 a multiple ground to the winding 15 of the relay 350, and at its armature 233 completes an energizing circuit for the winding of the relay 370, this circuit extending from ground at the armature 233, over the conductor 239 and through the winding of the relay 370 to battery. 20

In response to the completion of its energizing circuit the relay 370 operates and at its armature 371 closes a locking circuit for itself which extends by way of this armature, the conductor 301, the armature 346, the conductor 302, the armature 242 and associated contact of the relay 240, the conductor 412, the contact 419 to ground at the contact spring 420 of the night switch 424. The relay 370 also completes at its armature 372 and associated front contact the energizing circuit for the answer lamp 401. This circuit extends from battery at the lower terminal of the relay 470' through the winding of the relay 470', the contact spring 409 of the switch 470, the conductor 472, the lamp 401, the conductor 408, the 35 armature 282 and associated contact of relay 280, and the conductor 266 to ground at the armature 372 and associated front contact of the relay 370. The answer lamp 401 and the busy lamp 400 are now both lighted, indicating to the operator that 40 an incoming call from the central exchange has been extended by way of the trunk line 11 to the private exchange and awaits her attention. The trunk line equipment is now conditioned for the extension of the connection to the desired private 45 line by the operator. In this connection it is pointed out that following the completion of the ringing operation at the central exchange the relay 360 restores to interrupt at its armature 361 the circuit of the relay 230. As a consequence 50 this latter relay restores to connect at its armatures 231 and 232 the line conductors 28 and 29, respectively, to the line conductors 215 and 214, respectively. Restoration of the relay 230 also opens at its armature 233 the original energizing 55 circuit of the relay 370, and at its armature 234 opens the multiple ground circuits to the relays 340 and 350.

The operator or attendant answers the call by shifting the answer switch 425 associated with the 60 trunk line 11 from its normal to its off-normal trunk answer position to close the spring 402 to its associated contact 428 and thereby complete an energizing circuit for the relay 220, this circuit extending from ground at the armature 431 65 of the switch 426 by way of contact 432, conductor 444, spring 402, contact 428, answer conductor 400 and the winding of relay 220 to battery. Operation of the switch 425 to the answer position also prepares at the spring 403 and its 70 associated contact 409 an energizing circuit for the relay 250, this circuit being held open at the contact spring 436 of the trunk connect switch 426.

When the relay 220 operates in response to its 75

energization as above described, it pulls up its armatures 221 and 222 to connect the operator's telephone set 500 across the conductors 214 and 215 by way of the conductors 228 and 229. This relay also completes at its armature 223 an energization circuit for the relay 240, which circuit extends from ground at the armature 223 over the conductor 236, the closed armature 355, the conductor 217 and through the winding of relay 240 to battery. The relay 220 also prepares at its armature 225 a path for connecting the 100 ohm resistor 267 across the conductors 25 and 27, this resistor being arranged to constitute a bridge across these conductors and functioning to cause operation of the line equipment at the selector switch 33' to prepare the local switch train of the private exchange to be responsive to transmitted dialing impulses. In addition, the relay 220 prepares, at its armature 224, a locking circuit for the relay 250.

When the relay 240 operates, it closes at its armature 241 a locking circuit for itself, which extends from this armature over the conductor 406 to ground at the spring 407 of the trunk switch 425. At its armature 249, the relay 240 completes obvious energizing circuits for the relay 310 and the upper winding of the relay 260. The relay 260 is, however, not operated at this time as the excitation supplied by the upper winding 30 of this relay is insufficient to cause the operation thereof. The relay 240 also completes, at its armature 245, the talking loop extending from the operator's telephone to the central exchange and at its armatures 244 and 246 prepares the normally uncompleted talking loop extending from the operator's telephone by way of the line circuit comprising the conductors 25, 26 and 27 and the line switch 33' to the called line. Operation of these armatures also connects the resistor 267 across the conductors 25 and 27 to cause the operation of the line switch 33' which results in the extension of the loop to a selector switch such as 20. The relay 240 also disconnects, at its armatures 247 and 248, the winding terminals of the relay 210 from the line conductors 214 and 215; interrupts, at its armature 242, the previously-traced locking circuit for the relay 370; removes, at its armature 249, the shunt from the condenser 278; and at its armature 243 closes an energizing circuit for the supervisory lamp 410, this latter circuit extending from ground at the armature 261 through the armature 243, over the conductor 407 and through the filament of the lamp 410 to battery at the contact spring 411 and associated contact of the switch 470.

When the relay 370 restores, it opens at its armature 371 a further point in its locking circuit and, at its armature 372 interrupts the previously-traced circuit of the answer lamp 401, thus extinguishing the same. When the relay 310 operates, in response to the completion of its energizing circuit at the armature 249', it immediately completes, at its armature 316, a multiple locking circuit for the relays 340 and 350, and at its armature 311 completes a multiple locking circuit for the relay 320. At its armature 314, the relay 310 closes multiple ground to the C conductor 218 and at its armature 315 it prepares a circuit for the energization of the relay 320. The relay 310 also closes, at its armature 312, multiple ground to the ringing machine start conductor 227 and at its armature 313 removes the winding of the relay 330 from across the line conductors 75 23 and 24, permitting the latter relay to restore

and open the original holding circuits for the relays 340 and 350. The latter relays remain operated, however, due to the completion of the previously-described multiple locking circuit extending from ground at the armature 316 of the 5 relay 310.

With the equipment in this condition, a talking loop is established between the operator's telephone and the central exchange, this loop extending from the terminals 465 and 466 over conductors 228 and 229, armatures 255 and 256, armatures 221 and 222 and conductors 214 and 215 to the windings of the repeater 200 from whence it extends over conductors 23 and 24 to the central exchange. The operator may now receive from the calling party or the operator in the central exchange the name or number of the desired party in the private exchange. It is pointed out here that the loop extending to the line switch 33' and the succeeding automatic switch train in the private exchange is held isolated from the central exchange talking loop at the armatures 258 and 259 of relay 250 and at the armatures 272 and 273 of the relay 270, neither of these relays being operated at this time. It is further pointed out that the local switch train comprising the switches 33', 20, and 18 is prepared to respond to impulses transmitted from the impulsing device 458, since the closure of the resistor 267 across the line conductors 25 and 27 upon the operation of the relay 220, caused the line switch 33' to operate and select an idle selector switch such as the switch 20 for extending the loop to an idle connector in the proper group.

Following the receipt of the information necessary to the completion of the call and in order to render the impulsing device effective to cause the required operation of the automatic switches in the private exchange, the operator momentarily operates the self-restoring connect key switch 426 to close ground from the spring 435 to its associated contact 436, thereby to complete the energizing circuit for the relay 250. This circuit extends from ground at the contact spring 435 by way of the contact 436, the contact 403, the contact 409, the conductor 405, and through the winding of the relay 250 to battery. This relay operates immediately to close at its armature 251, the previously prepared locking circuit for itself and to disconnect, at its armatures 255 and 256, respectively, the central exchange loop from the conductors 228 and 229 leading to the operator's telephone and to connect these conductors to the conductors 25 and 27 leading to the line switch 33'. It will be noted that the armatures 258 and 259 are actuated by the armatures 255 and 256, respectively, to disconnect the conductors 27 and 25, respectively, from the multiple conductors 276 and 277, respectively, leading to the armatures 273 and 272, respectively, so that the resistor 267 is removed from across the conductors 25 and 27, and the bridge comprising the operator's substation is substituted therefor. In addition, the disconnection of the conductors 274 and 275 from the conductors 276 and 277, respectively, permits the relay 270 to operate, which it does before dialing, while maintaining the central exchange loop isolated from the loop to the line switch 33' over which the dialing impulses are transmitted. The relay 250, at its armature 253, short circuits the condenser 278, thereby completing a metallic circuit to the line switch 33' for dialing, and at its armature 252 completes an obvious energizing 75

circuit for the upper winding of the line relay 210. At its armature 257, the relay 250 prepares an obvious multiple locking circuit for the relay 240, this circuit being completed upon the operation 5 of the relay 210 and, at its armature 254, the relay 250 completes an energizing circuit for the relay 270, this latter circuit extending from ground on the control or C conductor 26, following the extension of the private exchange loop to the line 10 switch 33' and the resulting operation of its associated equipment over the initiating circuit including the resistor 267.

When the relay 270 operates, it closes a locking circuit for itself at its armature 271, prepares a 15 locking circuit for the relay 280 at its armature 274, and at its armatures 272 and 273, further prepares a loop circuit from the central exchange to the called line by way of the line switch 33'.

In response to the energization of the upper 20 winding of the relay 210, this relay operates to close at its armature 212 a multiple loop circuit to the central exchange, to complete, at its armature 213, the previously prepared multiple locking circuit for the relay 240, and to complete, at its 25 armature 211, a multiple circuit for the relay 310 and the upper winding of the relay 260. At this point the excitation supplied by the upper winding of this latter relay is insufficient to cause operation thereof.

30 At this point the operator's telephone is connected to the line equipment at the switch 33' over the loop circuit extending from the terminal 465, through contacts of the switches 426 and 427, the conductor 229, the armatures 255 and 258 of the relay 250, the conductor 274, the armature 246 of relay 240, the conductor 27, the windings of the line relay in series with battery at the line switch 33', the conductor 25, the armature 244 of relay 240, the conductor 275, the armatures 256 and 259 of relay 250 and over the conductor 228 to the terminal 466. The switch 33' then operates to connect the loop through to the first selector. The operator now receives dial tone over this circuit which is applied thereto in 45 the conventional manner in the local switch train of the private exchange.

The operator may now operate the impulsing device 458 to interrupt the loop circuit extending to the operated first selector in accordance with 50 the digits dialed, thereby to cause the extension of the connection in the previously described manner to the line of the called party. If this line is busy, busy tone will be returned over the loop to the operator in a conventional manner 55 and the operator may then inform the calling party to that effect and hold the incoming call until the called line is idle or abandon the call to disconnect the trunk 11, depending upon the instructions received, all in the manner described 60 in detail hereinafter.

If the called line is idle and the call is answered, the operator proceeds to complete the talking loop between the calling and called parties. This is accomplished by operating the answering key switch 425 to its normal position, thereby to remove, at the spring 402 and its associated contact 428, ground from the conductor 404 with the result that the energizing circuit for the relay 220 is interrupted and the armatures of this relay 70 restore to their normal position. Operation of the key switch 425 to its neutral position also interrupts, at the spring 403 and associated contact 409, the original and previously-traced energizing circuit for the relay 250 so that, when the relay 220 75 restores to interrupt at its armature 224 the lock-

ing circuit for the relay 250, the latter relay also restores.

When the relay 220 restores, in addition to interrupting the locking circuit for the relay 250, it opens at its armatures 221 and 222 the circuit to 5 the line conductors 214 and 215 for connecting these conductors to the conductors 228 and 229 leading to the operator's telephone. In addition, the relay 220, at its armature 225, opens an additional point in the bridging path across the conductors 214 and 215 and including the resistor 267. The relay 220 also opens, at its armature 223, the previously-traced multiple locking circuit for the relay 240.

When the relay 250 restores in response to the 15 interruption of its energizing circuit as described above, it opens a further point in its locking circuit at its armature 251 and, at its armatures 258 and 259, connects the central exchange loop to the private exchange loop, thereby to complete 20 the talking loop between the calling and called lines. This relay also operates to open at its armatures 254 and 257, respectively, the original energizing circuit for the relay 270 and a further point in the previously-traced locking circuit for 25 the relay 240. In addition, the relay 250 at its armature 252 opens the energizing circuit for the upper winding of the relay 210, thereby causing this relay to restore, but without effect at this 30 time.

It will be seen that with the equipment in this condition the lower winding of the relay 260 is connected across the conductors of the talking loop extending to the called party line in series with the 500 ohm resistor 268. It will further be 35 seen that the line conductors 228 and 229 extending to the operator's telephone are disconnected from the talking loop at the armatures 221 and 222 of the relay 220.

When the called party answers by lifting his 40 receiver from its hook, battery is reversed back over the loop circuit extending to the line conductors 214 and 215 in the conventional manner, so that, when the established private exchange loop is connected to the central exchange loop 45 upon the operator's restoration of the switch 425 to normal, the excitation furnished by the two windings of the relay 260 is cumulative and this relay operates. In response to its operation, an obvious energizing circuit for the relay 280 is 50 completed at the armature 261. With the same operation, ground is removed at this armature from the conductor 407 so that the previously-traced energizing circuit for the supervisory lamp 410 is interrupted and this lamp is extinguished to 55 indicate to the operator that the proper operations have occurred to complete the loop between the calling and called lines. In addition, the relay 260, upon operating, at its armature 263, prepares a circuit including the armature 372 and 60 the conductor 266 for energizing the answer lamp 401 and, at its armature 262, opens a point in an alternate energizing circuit for the same lamp.

When the relay 280 operates, it closes the previously prepared locking circuit for itself at its 65 armature 281 and closes its armature 282 to the associated back contact to prepare a circuit extending by way of the conductor 408 for the energization of the answer lamp 401.

With the system in this condition, all of the 70 key switches at the operator's station are in their neutral or normal positions and only the busy lamp 400 is illuminated to indicate that the trunk line 11 is being used. As regards the line equipment associated with the trunk line 11 and shown 75

in Figs. 2 and 3, the relays 210, 220, 230, 250, 330, 360 and 370 are restored and the remaining relays shown are in an operated condition. The talking loop established by the operated relays 5 240, 260, 270, 280, 310, 320, 340, and 350 extends from the central exchange, over the trunk line 11 comprising the conductors 23 and 24, through the repeater 200, and over the conductors 214, 215, 276, 277, 274, 275 to the line 35 comprising the 10 conductors 25, 26 and 27.

Monitoring

If for any reason it is necessary or desirable 15 to monitor the connection established in the manner described above, the operator may connect the telephone 500 to the line conductors 214 and 215 over which the transmission is taking place by operating the switch 425 to its left off-normal or answer position, thereby closing, 20 over the conductor 404, the previously traced energizing circuit for the relay 220. Operation of this relay causes the line conductors 228 and 229 to be connected across the talking loop conductors at the armatures 222 and 221, respectively. The operation of the remaining armatures 25 of this relay has no effect at this time since the circuits in which they are individually included are either held open or multiplied at the armatures of certain of the other relays. With 30 the equipment in this condition, the operator may listen to the ensuing conversation or break in on the conversation, as desired. It is pointed out that, with the system in this condition, the condenser 278 inserted in the conductor 229 is included in the circuit extending to the operator's 35 telephone as soon as the relay 250 is, as noted above, restored and the relay 240 is operated. The presence of this condenser prevents undue transmission loss between the calling and called 40 substations. Restoration of the switch 425 to its normal position obviously opens the energizing circuit for the relay 220, permitting this relay to restore to its normal position thereby to open the monitoring connection.

45 Splitting the established connection

It may for some reason be necessary for the 50 operator to split a connection established in the above-described manner and to connect her telephone to the called private line to the exclusion 55 of the calling party. This may be accomplished by operating the switch 425 to the left off-normal or answer position to establish a monitoring connection, as described above, and thereafter operating the switch 426 momentarily to its right off-normal position to close ground at the contact 60 spring 435 of this switch to the conductor 405 and thereby complete the previously traced energizing 65 circuit for the relay 250. This relay operates to complete a locking circuit for itself at its armature 251, to close a shunt around the condenser 278 at its armature 253, thereby completing a metallic bridge circuit through the operator's telephone 500 for holding the local switch train operated, and to close at its armatures 255, 256 and 258, 259, the operator's telephone to the talking 70 loop extending to the called line. Operation of the armatures 258 and 259 also disconnects the last-mentioned talking loop from the central exchange talking loop so that the operator may talk to the called party to the exclusion of the calling party. The relay 250 also completes, at its armature 252, an energizing circuit for the upper winding of the relay 210, which relay operates its 75 armatures to close various multiple circuits, but

without effect at this time. When the loop extending to the lower winding of relay 260 is opened in response to the operation of the relay 250, this relay restores, opening at its armature 261 the original energizing circuit for the relay 280 and completing at this same armature a circuit extending by way of the conductor 407 for energizing the supervisory lamp 410. The relay 280 is, however, maintained in its operated position by virtue of the completed holding circuit 10 extending by way of its armature 281 and the armature 274' to ground.

In order to re-complete the talking loop between the calling and called parties and to disconnect the operator's telephone from this loop, 15 the operator actuates the answer switch 425 to its normal position, thereby opening at the contact spring 402 the previously traced energizing circuit for the relay 220 to permit this relay to restore. When the relay 220 restores, it opens the 20 circuits holding the relays 250 and 210 operated, thereby permitting these latter relays to restore. When the relay 250 falls back, it re-completes the talking loop between the calling and called parties in a manner believed to be obvious from 25 the preceding description, and when this loop is completed the relay 260 re-operates to open at its armature 261 the previously traced energizing circuit for the supervisory lamp 410. The apparatus is now restored to the condition which 30 prevailed before the extended talking loop between the calling and called parties was interrupted at the operator's station.

Release of the connection by the private exchange 35 operator

When the conversation over the established connection is terminated and the called party on the private line hangs up, battery is again reversed back over the talking loop extending from 40 the called line to the repeater 200, thereby differentially energizing the windings of the relay 260 and causing this relay to restore. At its armature 261, the relay 260 interrupts the original energizing circuit of the relay 280 and completes 45 an energizing circuit, extending by way of the armature 243 and the conductor 407, for the supervisory lamp 410, this circuit being completed to battery at the spring 411 of the night alarm key switch 470. The relay 280 does not restore 50 in response to the restoration of the relay 260 since its energizing circuit is held completed over the locking path including the armature 281. At 55 its armature 262, the relay 260, upon restoring, completes an energizing circuit for the answer lamp 401, this circuit extending from battery through the winding of the relay 470', the spring 409 and associated contact of the key switch 470, the conductor 472, the filament of the lamp 401, the conductor 408, the armature 282 of relay 280, 60 the armature 262 of relay 260, and the conductor 269 to ground at the armature 372 of the relay 370. Thus, all of the lamps 400, 401 and 410 are 65 illuminated, indicating to the operator that the trunk line 11 and its associated equipment is now idle and may be released for further use.

The release of the equipment is initiated by 70 momentarily operating the switch 425 to its right off-normal or trunk release position, thereby to interrupt at its spring 407 and associated contact 75 the holding circuit for the relay 240. This relay restores and at its armatures 244 and 246 opens the loop including the conductors 25 and 27 extending to the line equipment of the line switch 33', thereby initiating the release of the latter 75

equipment in the usual manner. At its armature 245, the relay 240 upon restoring, opens the loop circuit extending by way of the conductors 23 and 24 constituting the trunk line 11 to the central exchange. The relay 240 also, upon restoring, opens at its armature 243 the previously traced energizing circuit for the supervisory lamp 410 and, at its armatures 247 and 248, reconnects the windings of the relay 210 across the line conductors 214 and 215. This latter operation is without effect, however, since at this time there is no bridge across the enumerated conductors 214 and 215. Restoration of the relay 240 also closes at the armature 242 a point in the locking circuit for the relay 370 and closes at the armature 249 a shunt around the condenser 278 included in series with the two halves of the conductor 229.

When, as above described, the line equipment at the line switch 33' is released, ground is removed from the C conductor 26 thereby interrupting the holding circuit for the relay 278 and causing this relay to restore. In response to the restoration of the relay 278, a further point in its locking circuit is opened at the armature 271 and the holding circuit for the relay 280 is opened at the armature 274 so that this latter relay restores. Restoration of the armatures 272 and 273, of the relay 270, to their respective normal positions has no effect at this time. When the relay 280 restores its armature 282, it interrupts the previously traced energizing circuit for the answer lamp 401, causing this lamp to be extinguished and also opens, at its armature 281, a further point in its own holding circuit.

In response to the restoration of the relay 240, the relay 310 restores to reconnect at its armature 313 the relay 330 across the line conductors 23 and 24. The latter relay operates, in the event the equipment at the central exchange has not cleared out, to close the holding circuit at its armature 331 for the relay 340, which latter relay closes, at its armature 341, the holding circuit for the relay 320 before this latter slow-to-release relay restores to remove ground at its armature 321 from the C conductor 218. The relay 330 then retains ground on the C conductor 218 through the retention of the relays 320 and 340 in their respective operated positions, thereby maintaining the trunk busy in the bank contacts of the connector switch in which the line comprising the conductors 28, 29 and 30 terminate. When the equipment at the central exchange associated with the trunk line 11 is released, battery is removed from across the conductors 23 and 24 with the result that the relay 330 restores to open at its armature 331 the holding circuit for the relay 340, permitting this relay to restore to normal. When the relay 340 restores, it opens at its armature 341, the energizing circuit for the relay 320, which relay in turn restores and removes ground, at its armature 321, from the C conductor 218, thus marking the trunk line 11 as idle in the bank contacts of the connector switches in which the line comprising conductors 28 to 30, inclusive, terminate. All of the equipment associated with the trunk line 11 and illustrated in Figs. 2, 3, and 4 is now in its normal or idle condition, ready for further use.

70 *Transfer of operator telephone from private exchange loop to central exchange loop*

As pointed out above, in the event a called line in the private exchange is busy, the operator receives busy tone over the loop extending from

the telephone 500 to the called line, indicating the busy condition of the line, and may, thereafter, communicate this fact to the calling party by disconnecting the telephone 500 from the loop extending to the called line and connecting the 5 same to the loop extending to the calling party, at the same time releasing the local switch train associated with the loop extending to the called line. This can be accomplished by momentarily operating the switch 426 to its left off-normal 10 position to interrupt at its contact spring 431 and the associated contact 432 the previously traced energizing circuit for the relay 220, thereby permitting this relay momentarily to restore to break at its armature 224 the established locking circuit for the relay 250. All of the armatures of the relay 220 necessarily restore but are reoperated in response to the reclosure of the energizing circuit for this relay at the contact 432 following the operator's release of this non-locking switch 426 and its consequent restoration to normal. During the period of restoration of the relay 220, however, the relay 250 restores to further open at its armature 251 a point in its own locking circuit and consequently this relay remains in its restored position after the relay 220 is again operated. With the equipment in this condition, the conductors 228 and 229 leading to the operator's telephone 500 are connected to the conductors 215 and 214, respectively, included in 15 the loop extending to the central exchange, this connection comprising the armatures 256 and 255 and the armatures 222 and 221. As thus connected, the operator may converse with the calling party and receive instructions as to whether 20 the call should be held or the established connection should be released in the manner set forth above. Obviously, when the relay 250 restores, all of its armatures are restored, but without effect at this time. If the calling party desires that 25 the connection already established to the attendant's cabinet not be held until such time as the called line is idle, the established connections as described above may be released in the previously 30 described manner.

Holding of calls at operator's station

If, however, the calling party desires that the call be held at the attendant's cabinet until such time as the called line is idle, this may be accomplished without tying up the operator's equipment by operating the answer key switch 425 to its normal position, thereby to interrupt the previously traced energizing circuit for the relay 220, which relay restores and, at its armatures 221 and 222, disconnects the operator's telephone from the line conductors 214 and 215, thereby 35 freeing the operator's equipment for use in connection with the other central office trunk lines extending to the private exchange. With the equipment in this condition, the busy lamp 400 and the supervisory lamp 410 are lighted while the answer lamp 401 is extinguished, thus indicating to the operator that a call is being held on the trunk line 11 so that she may from time to time attempt to complete the desired connection or converse with the calling party as desired. In view of the foregoing description, the manner in which the operator may again connect her telephone to the line comprising the conductors 40 25 and 27 extending to the line switch 33', to call the desired telephone, is believed to be obvious and is, therefore, omitted.

In the event that the operator at the station forgets she is holding a call on the trunk line 11 45 75

Night service

or if for any other reason it is desired to signal the operator at the station 13 over a trunk line which is being held, this may be accomplished by the operator in the central exchange applying 5 ringing current across the line conductors 23 and 24 of the trunk line 11, to cause energization of the alternating current relay 360. When this relay operates, it closes its armature 361 to ground, to complete the energizing circuit for the relay 10 10 230. The latter relay at its armature 233 closes an energizing circuit for the relay 370, which relay in turn pulls up its armature 372 to complete, by way of the conductor 266, the armature 15 282 and the conductor 408, a circuit for illuminating the answer lamp 401. Since the locking circuit for the relay 370 is, under the conditions stated, held open at the armature 242 of the energized relay 240, the relay 370 may periodically be energized in the above-described manner to 20 20 flash the lamp 401 and attract the attention of the operator. By this method, a call is prevented from being held indefinitely at the operator's station due to the forgetfulness of the operator thereat.

25 *Called line is not answered*

In the event the called line is not answered following the initiation of a call thereto from the operator's station, ring-back tone is transmitted 30 over the loop extending to the operator's station, indicating to the operator the condition which prevails. Under these conditions, the operator may have instructions to call an alternative private line, or may believe that the called party may be reached by calling over another 35 private line to another telephone in the same office, for example. In either case, and in order to establish the desired second connection, it is necessary that the local switch train be released without disconnecting the operator's telephone 40 40 500 from the loop extending to this switch train. It will be remembered that the condition of the apparatus is, under the circumstances stated, such that the switch 425 is in its left-hand off-normal, or answer position and the relays 220 and 45 250 are, among others, operated. Obviously, it is desirable to release the local switch train without disturbing the operated condition of the two relays mentioned. This may be accomplished by momentarily operating the switch 427 to its right-hand off-normal position to interrupt, at its contact springs 437 and 438, the metallic bridge circuit holding the local switch train operated and 50 extending over the line conductors 228 and 229. Operation of the switch 427 to this position also 55 closes the contact springs 439 and 440, but without effect since such closure merely completes a multiple energizing circuit for the relay 250 by way of the contact spring 403 of the switch 425 and conductor 405, this relay being already 60 in its operated position. Interruption of the bridge circuit at the contact springs 437 and 438 permits the line equipment at the selector switch 33' to initiate the restoration of the local switch train in a conventional manner. Following 65 the momentary operation of the switch 427, the contacts 437 and 438 are again closed to re-complete the bridge circuit and thereby re-condition the local switch train to be responsive to dialing impulses transmitted from the impulsing 70 device 458 at the operator's station. The manner in which the operator establishes a talking loop through the local switch train to the second line is exactly the same as that described above in connection with the first called line and need 75 not be repeated.

As pointed out above, equipment is provided for the extension of calls from the central exchange directly to a predetermined party line during those periods when no operator is on duty at the operator's station. This equipment includes the line conductors 264 and 265 connected respectively to the line conductors 28 and 29 and extending to contact springs in the night switch 424. In the normal position of this switch, the conductors 264 and 265 are open circuited at their respective contact springs 422 and 415. When, however, the attendant or operator is off duty, this key switch is locked operated in its off-normal position to close its contacts 422, 423 and 414, 415, thereby to extend the line conductors 264 and 265 to the line equipment of the predetermined substation designated for night service. Operation of this switch to its off-normal position also interrupts, at its contact spring 418, the energizing circuit for the answer lamp 400 and, at its contact 416, applies ground to the conductor 413 extending to the control conductor 218, thereby to mark the trunk line 11 as busy in the bank contacts of the selector switches to which conductors 28 to 30, inclusive, extend. At its contact 419, the switch 424 when operated to its off-normal position opens a point in the holding circuit for the relay 370, this relay not being required for night service, since it performs only supervisory functions.

In addition to operating the night switch 424 to its off-normal position, the operator may, if desired, operate the night alarm switch to its left off-normal position where it locks, thereby preparing, at the contact springs 492 and 493, an energizing circuit for the buzzer or bell 494, this circuit being held open at the armature 471 of the relay 470.

When the night switch 424 is operated to its off-normal position in the manner described and when a call is initiated from the night telephone to the central exchange, the relay 210 is operated over the loop circuit comprising the conductors 214 and 215 extending from the repeater 200 to the night telephone, which loop circuit is completed upon the night operator's removal of his telephone set from its hook switch. The operation of the relay 210 initiates the sequential operation of the relays 310 and 320, in the order named, thereby extending the connection to the central exchange in a manner identical to that described above for calls to this exchange initiated on private lines in the branch office. The release of this established connection is also effected in the same manner as that described above for the type of call noted.

On an incoming call from the central exchange to the branch exchange by way of the trunk line 11 and with the night switch 424 and the night alarm switch 470 operated to their respective off-normal positions, the connection of battery across the conductors 23 and 24 energizes the relay 330, which relay in turn closes an energizing circuit for the relay 340 at its armature 331. The relay 340, at its armature 345, completes an energizing circuit for the relay 350, which relay, at its armature 354, connects the winding of the alternating current relay 360 across the line conductors 23 and 24. The relay 350 also connects ground to the ringing machine start conductor at its armature 351, completes an energizing circuit for the relay 320 at its armature 352 and completes a holding circuit for itself at its armature 353.

The relay 320 now operates to extend, at its armature 322, the central office loop to the armature 212 of the relay 210 and to disconnect, at its armature 323, ground from the positive line conductor 23. The relay 320 also closes multiple ground to the control conductor 218 at its armature 321 and closes a locking circuit for itself at its X contacts and the armature 324.

When ringing current is applied to the conductors 23 and 24 at the central exchange, the relay 360 energizes and, at its armature 361, closes the energizing circuit comprising the conductor 237 for the relay 230. The latter relay operates to apply, at its armatures 231 and 232, direct generator current to the conductors 264 and 265 leading to the night telephone and to complete, at its armature 233, an energizing circuit for the relay 370. The current from this generator energizes a signaling device at the night telephone indicating to the night operator that a call is to be answered. Operation of the relay 370 completes an energizing circuit for the relay 470', this circuit extending from ground at the armature 372 by way of the conductor 266, the armature 282, the conductor 408, the lamp 401, the contact spring 409 through the winding of the relay 470' to battery. When the relay 470' operates it completes an obvious circuit for the signaling device 494. The device 494 continues to operate during such time as ringing current is applied to the conductors 23 and 24 to hold the chain of relays 360, 230, 370 and 470' operated. When ringing current is removed from the conductors 23 and 24, the relay 360 restores, thereby opening the energizing circuit of the relay 230 at its armature 361 and permitting the latter relay to restore. When the relay 230 restores, it interrupts the operation of the signal device 494 by causing the relays 370 and 470' to restore, and returns its armatures 231 and 232 to the line conductors 214 and 215 extending to the repeater 290, thereby further preparing the loop between the central exchange and the night telephone. When the night attendant answers the call by lifting his receiver from its hook, a bridge is connected across the conductors 264 and 265, completing over the loop comprising the conductors 264 and 265 a circuit for energizing the relay 210. This relay operates and completes at its armature 212 the talking loop extending from the night telephone to the central exchange. Operation of the relay 210 also closes the previously traced energizing circuit for the relay 310, which relay operates to disconnect, at its armature 313, the winding of relay 330 from across the line conductors 23 and 24, thereby opening the original energizing circuit for the relay 340. The latter relay is, however, held operated by a locking circuit extending to ground at the armature 316 of the relay 310 so that the connections as thus established are not disturbed.

When the conversation is terminated and the telephone at the night station is returned to its hook, the previously traced energizing circuit for the windings of relay 210 is interrupted, permitting this relay to restore and cause the sequential restoration of the relays 310, 340, 320 and 350, in the order named, providing, of course, the line equipment associated with the trunk line 11 in the central exchange has been cleared. If the call has not been cleared out at the central exchange, battery remains across the conductors 23 and 24, so that when the relay 310 restores, the relay 330 operates to close at its armature 331 a holding circuit which maintains the relays

320, 340 and 350 in their operated positions. When the connection is cleared out at the central exchange, however, battery is removed from the conductors 23 and 24, permitting the restoration of the relay 330, followed by the restoration of the relays 340, 350 and 320, in the order named. 5

Secretarial or executive service

As pointed out above, in addition to the service features already described, the arrangement includes means whereby secretarial or executive service may be provided for at least predetermined ones of the private lines in the private exchange. Thus, an executive or other important official may desire to talk to a party whose location or telephone number is not immediately available. Under these circumstances, he may dial at his substation a predetermined digit known perhaps only to a few individuals, causing the selector switch 20 to extend the connection from the calling line by way of the information trunk line 31 directly to the operator's station. When this occurs, ground is closed at the selector switch 20 to the control conductor 490, thereby completing an energizing circuit for the information trunk lamp 484, which circuit extends through this lamp, the contact spring 409 and the winding of the relay 470', to battery. Illumination of the lamp 484 indicates to the operator that a call on the information trunk 31 is awaiting attention, whereupon the switch 482 may be operated to its off-normal position to form a talking loop between the telephone 500 and the calling telephone. Such operation of the switch 482 connects the operator's telephone by way of the line conductors 445 and 446 to the line conductors of the line 31 in an obvious manner. The operation of this switch also closes ground to a second control conductor 491, causing the operation of line equipment associated with the information trunk 31, which results in the interruption of the energizing circuit for the lamp 484. Following the transmission of the desired information to the operator, the calling party restores his telephone to its hook and the operator restores the switch 482 to normal, thereby releasing the equipment involved and including the information trunk 31 and the operator's telephone 500. 20 25 30 35 40 45 50 55 60 65 70 75

If the operator believes that the desired party can be located at a telephone connected to one of the private lines, this line may be called without appropriating one of the central exchange trunk lines, such as the line 11, by means of the operator's local switch 483 and associated line 32 extending by way of the line switch 33 to certain ones of the selector switches, such, for example, as the selector switch 20. Thus, the operator may call any desired private line by actuating the switch 483 to its off-normal position to connect the substation 500 by way of the line conductors 445 and 446, the contacts of the switch 483 and the line 32 to the line switch 33. Closure of the substation bridge circuit across the conductors of the line 32 causes the line switch 33 to prepare the local switch train to be responsive to dialing impulses, in the conventional manner. In this way the operator may by dialing the desired number establish a connection from the telephone 500 to the desired private line and, if the desired party is located, may communicate the name and number of the executive. Following this, the established connection may be released by restoring the switch 483 to its normal position to initiate the release of the local switch 70 75

train. Subsequently, the party receiving the information may call the executive in the manner previously described in connection with the description of the system, generally, with particular reference to Fig. 1. From the immediately preceding description it will be apparent that the operator may, by using the switch 483 and the equipment associated therewith, establish a connection to any of the lines in the private exchange without using the equipment associated with any of the central exchange trunk lines. This feature is desirable since the operator's local calls, which may constitute a large number, do not interfere with the regular use of the trunk lines and hence, in many instances, reduces the number of trunk lines required.

If the party desired by the executive can only be reached over a connection by way of one of the central exchange trunk lines, the operator may connect the telephone 500 to an idle one of these lines, for example the line 11, by operating the switch 425 to its left-hand off-normal or answer position, thereby to close the previously traced energizing circuit for the relay 220. This relay, upon operating, connects at its armatures 221 and 222 the operator's substation 500 across the line conductors 214 and 215, thereby completing a metallic loop by way of the repeater windings 201 and 202 for energizing the relay 210 as described previously. This relay, upon operating, closes at its armature 211 an obvious energizing circuit for the relay 310, which latter relay, upon operating, causes the operation of the relay 320 in a manner previously described and also disconnects, at its armature 313, the winding of the relay 330 from across the line conductors 23 and 24. When the relay 320 operates, it closes, at its armature 321, ground to the C conductor 218, thereby marking the line 11 as busy in the bank contacts of the selector switches and completing the previously traced energizing circuit for the busy lamp 400. This relay also completes, at its armatures 322 and 323, a talking loop from the operator's substation to the central exchange and removes ground from the line conductor 24. The talking loop, as thus completed, may be extended to the desired line in the central exchange in the manner described in a preceding portion of the specification in connection with calls to the central exchange initiated on lines in the branch exchange. If the desired party is located, that party may be instructed to hold the call while the operator recalls the executive in the private exchange. This latter operation is accomplished by actuating the switch 426 momentarily to its right off-normal position, thereby to close at its contact springs 435 and 436 an energizing circuit for the relay 250. This relay operates to close, at its armature 251, its holding circuit, to complete, at its armature 257, an energizing circuit for the relay 240, to close, at its armature 252, a holding circuit for the relay 210, to close, at its armature 253, a shunt around the condenser 278, to prepare, at its armature 254, an energizing circuit for the relay 270 and to transfer at its armatures 255, 256, 258, 259 the operator's telephone from the central exchange talking loop to the uncompleted loop extending to the called line. From this point on, the completion of the talking loop to the called line, the connection of this loop to the central exchange talking loop and the disconnection of the operator's telephone from the last-mentioned loop are exactly the same as described above in connection with

an incoming call from the central exchange to a private line in the branch exchange.

From the foregoing description, it will be apparent that, when the operator's telephone 500 is disconnected from all lines and standing idle, all of the operator controlled key switches are in their normal or restored positions. Conversely, when the operator's substation 500 is connected to any one of the various talking loops described, the operator is aware of this fact not only by virtue of the various audible signals transmitted to the receiver 459 as a consequence of such connection and by the condition of the signal lamps such as the lamps 400, 401, 410 and 484, but also by the position of the various key switches such, for example, as the switches 425, 482 and 483. Thus, in order to monitor an established connection in the manner described above, it is necessary that the switch 425 be locked in its left off-normal or answer position and, further, that the lamps 400 and 410 be illuminated. As a consequence of this mode of operation, the possibility of mistakes on the part of the operator is minimized, and it is practically impossible for any one of the central exchange trunk lines, such, for example, as the line 11, to be tied up when it is in fact idle. It will further be noted that the various types of services rendered are accomplished by the operation of a very small number of operator controlled switches, the various functions being concentrated in these switches to the greatest extent. Thus, the means for preparing the local switch train in the central exchange to be responsive to dialing impulses transmitted from the operator's substation 500, for establishing a talking loop between the central exchange and a telephone in the private exchange, for monitoring such a connection, and for releasing such a connection are individually responsive to the operation of the switch 425 to predetermined positions. Again, the means for transferring the operator's telephone from an established central exchange talking loop to a previously prepared but uncompleted private exchange talking loop and for restoring the operator's telephone to a connection with the central exchange loop and simultaneously initiating the release of the established local switch train associated with the private exchange talking loop, are individually both responsive to the momentary operation of the switch 426 to predetermined positions. Finally, the means for releasing the local switch train associated with an established connection between one of the private lines and the operator's telephone without disconnecting the operator's telephone from the restored private exchange loop and thereafter re-preparing the switch train to be responsive to dialing from the operator's telephone, and for simultaneously splitting an established connection between a private exchange loop and a central exchange loop, releasing the local switch train holding the loop extended to the called private lines and connecting the operator's telephone across the line conductors extending to the local switch train are individually responsive to the momentary operation of the switch 427 to predetermined positions. These various means include means comprising the two relays 220 and 250, which relays are directly responsive to the operation of one or more of the switches noted to one or more predetermined positions. This feature of concentrating the switch operations in a few relay controlled switches and of connecting the relays to perform the actual switching operations, results

in a very simple circuit arrangement while retaining the flexibility of operation normally found only in more complicated systems.

While there has been described what is at present considered to be the preferred embodiment of the invention, it will be apparent that various modifications may be made therein, and it is intended in the appended claims to cover all such modifications as fall within the true spirit and scope of the invention.

I claim:

1. In a telephone system, a central exchange, a private exchange, a trunk line extending between said exchanges, private lines in said private exchange and accessible to said trunk line, at least a portion of said lines having private telephones individually associated therewith, an operator's station, an operator's telephone at said station, means for establishing a talking loop between one of said private telephones and said central exchange, said loop extending by way of said trunk line and the line associated with said one of said telephones, an operator controlled switch at said operator's station, means operative in response to the momentary operation of said switch to a predetermined position for initiating or completing a predetermined service in connection with calls extending over said trunk line and means independent of said switch for retaining said last-mentioned means operated.

2. In a telephone system, a central exchange, a private exchange, a trunk line extending between said exchanges, private lines in said private exchange and accessible to said trunk line, at least a portion of said lines having private telephones individually associated therewith, an operator's station, an operator's telephone at said station, means for establishing a talking loop between one of said private telephones and said central exchange, said loop extending by way of said trunk line and the line associated with said one of said telephones, an operator controlled switch at said operator's station, said switch having a normal position and at least one off-normal position, means operative in response to the momentary operation of said switch to a predetermined off-normal position for initiating or completing a predetermined service in connection with calls extending over said trunk line, and means independent of said switch for retaining said last-mentioned means operated.

3. In a telephone system, a central exchange, a private exchange, a trunk line extending between said exchanges, private lines in said private exchange and accessible to said trunk line, at least a portion of said lines having private telephones individually associated therewith, an operator's station, an operator's telephone at said station, means for establishing a talking loop between one of said private telephones and said central exchange, said loop extending by way of said trunk line and the line associated with said one of said telephones, an operator controlled switch at said operator's station, means including at least one relay associated with said trunk line and operative in response to the momentary operation of said switch to a predetermined position for initiating or completing a predetermined service in connection with calls extending over said trunk line, and means independent of said switch for retaining said relay operated.

4. In a telephone system, a central exchange, a private exchange, a trunk line extending between said exchanges, private lines in said private exchange and accessible to said trunk line, at least

a portion of said private lines having private telephones individually associated therewith, an operator's station, an operator's telephone at said station, means for establishing a talking loop between one of said private telephones and said central exchange, said loop extending by way of said trunk line and the line associated with said one of said private telephones, a plurality of operator-controlled switches at said operator's station, means individually operative in response to the momentary operation of certain ones of said switches to predetermined positions for rendering predetermined services in connection with calls extending over said trunk line, and means independent of said switches for retaining said last-mentioned means operated.

5. In a telephone system, a central exchange, a private exchange, a trunk line extending between said exchanges, private lines in said private exchange and accessible to said trunk line, at least a portion of said lines having private telephones individually associated therewith, an operator's station, an operator's telephone at said station, means for establishing a talking loop between one of said private telephones and said central exchange, said loop extending by way of said trunk line and the line associated with said one of said private telephones, a plurality of operator-controlled switches at said operator's station, and means independent of said switches and individually responsive to the momentary operation of certain ones of said switches to predetermined positions for rendering predetermined services in connection with calls extending over said trunk line.

6. In a telephone system, a central exchange, a private exchange, a trunk line extending between said exchanges, private lines in said private exchange and accessible to said trunk line, at least a portion of said lines having private telephones individually associated therewith, an operator's station, an operator's telephone at said station, means for establishing a talking loop between one of said private telephones and said central exchange, said loop extending by way of said trunk line and the line associated with said one of said private telephones, a plurality of operator-controlled switches at said operator's station, and means including a plurality of relays associated with said trunk line and individually responsive to the momentary operation of certain ones of said switches to predetermined positions for rendering predetermined services in connection with calls extending over said trunk line.

7. In a telephone system, a central exchange, a private exchange, a trunk line extending between said exchanges, private lines in said private exchange and accessible to said trunk line, at least a portion of said lines having private telephones individually associated therewith, an operator's station; operator-controlled switches at said station individually having a normal position and being operable to at least one off-normal position, means including means responsive to the operation of one of said switches to a predetermined off-normal position for preparing a talking loop between one of said private telephones and said central exchange by way of said trunk line on a call to said private exchange routed over said trunk line, means responsive to the operation of said one of said switches to its normal position for completing said loop, and means responsive to the operation of another of said switches to a predetermined off-normal position for perform-

ing a predetermined service in connection with calls extending over said trunk line.

8. In a telephone system, a central exchange, a private exchange, a trunk line extending between said exchanges, private lines in said private exchange and accessible to said trunk line, at least a portion of said private lines having private telephones individually associated therewith, an operator's station, operator-controlled switches at said station individually having a normal position and being operable to at least one off-normal position, means including means responsive to the operation of one of said switches to a predetermined off-normal position for preparing a talking loop between one of said private telephones and said central exchange by way of said trunk line on a call to said private exchange routed over said trunk line, means responsive to the operation of said one of said switches to its normal position for completing said loop, and means responsive to the momentary operation of another of said switches to a predetermined off-normal position for performing a predetermined service in connection with calls extending over said trunk line.

9. In a telephone system, a central exchange, a private exchange, a trunk line extending between said exchanges, private lines in said private exchange and accessible to said trunk line, at least a portion of said private lines having private telephones individually associated therewith, an operator's station operator-controlled switches at said station individually having a normal position and being operable to at least one off-normal position, means including means responsive to the operation of one of said switches to a predetermined off-normal position for preparing a talking loop between one of said private telephones and said central exchange by way of said trunk line on a call to said private exchange routed over said trunk line, means responsive to the operation of said one of said switches to its normal position for completing said loop, and means responsive to the operation of another of said switches to a predetermined off-normal position for performing a predetermined service as regards the established talking connection comprising said loop.

10. In a telephone system, a central exchange, a private exchange, a trunk line extending between said exchanges, private lines in said private exchange and accessible to said trunk line, at least a portion of said private lines having private telephones individually associated therewith, an operator's station, operator-controlled switches at said station individually having a normal position and being operable to at least one off-normal position, means including means responsive to the operation of one of said switches to a predetermined off-normal position for preparing a talking loop between one of said private telephones and said central exchange by way of said trunk line on a call to said private exchange routed over said trunk line, means responsive to the operation of said one of said switches to its normal position for completing said loop, means responsive to the operation of another of said switches to a predetermined off-normal position for performing a predetermined service in connection with calls extending over said trunk line, and means including means responsive to the operation of said one of said switches to a second off-normal position for releasing the established connection comprising said talking loop.

11. In a telephone system, a central exchange, a private exchange, a trunk line extending between said exchanges, private lines in said private exchange and accessible to said trunk line, at least a portion of said private lines having private telephones individually associated therewith, an operator's station, operator-controlled switches at said station individually having a normal position and being operable to at least one off-normal position, means including means responsive to the operation of one of said switches to a predetermined off-normal position for preparing a talking loop between one of said private telephones and said central exchange by way of said trunk line on a call to said private exchange routed over said trunk line, means responsive to the operation of said one of said switches to its normal position for completing said loop, means responsive to the operation of another of said switches to a predetermined off-normal position for performing a predetermined service in connection with calls extending over said trunk line, and means including means responsive to the momentary operation of said one of said switches to a second off-normal position for releasing the established connection comprising talking loop.

12. In a telephone system, a central exchange, a private exchange, a trunk line extending between said exchanges, private lines in said private exchange and accessible to said trunk line, at least a portion of said private lines having private telephones individually associated therewith, an operator's station, operator-controlled switches at said station individually having a normal position and being operable to at least one off-normal position, means including means responsive to the operation of one of said switches to a predetermined off-normal position for preparing a talking loop between one of said private telephones and said central exchange by way of said trunk line on a call to said private exchange routed over said trunk line, means responsive to the operation of said one of said switches to its normal position for completing said loop, means responsive to the momentary operation of another of said switches to a predetermined off-normal position for performing a predetermined service in connection with calls extending over said trunk line, and means including means responsive to the momentary operation of said one of said switches to a second off-normal position for releasing the established connection comprising said talking loop.

13. In a telephone system, a central exchange, a private exchange, a trunk line extending between said exchanges, private lines in said private exchange and accessible to said trunk line, at least a portion of said lines having private telephones individually associated therewith, an operator's station, an operator's telephone at said station, an operator-controlled switch at said station, means including means responsive to the operation of said switch to a predetermined position for completing a talking loop from said operator's telephone to one of said private lines on a call from said central exchange routed over said trunk line to said one of said private lines, and means responsive to the momentary operation of said switch to another position for interrupting said talking loop and for completing a talking loop extending from said operator's telephone over said trunk line to said central exchange.

14. In a telephone system, a central exchange, a private exchange, a trunk line extending be-

- 5 between said exchanges, private lines in said private exchange and accessible to said trunk line, at least a portion of said lines having private telephones individually associated therewith, an operator's station, an operator's telephone at said station, an operator-controlled switch at said station, means including means responsive to the momentary operation of said switch to a predetermined position for completing a talking loop from said 10 operator's telephone to one of said private lines on a call from said central exchange routed over said trunk line to said one of said private lines, and means responsive to the momentary operation of said switch to another position for interrupting said talking loop and for completing a talking loop extending from said operator's telephone over said trunk line to said central exchange.
- 15 15. In a telephone system, a central exchange, a private exchange, a trunk line extending between said exchanges, private lines in said private exchange and accessible to said trunk line, at least a portion of said lines having private telephones individually associated therewith, an operator's station, an operator's telephone at said station, an operator-controlled switch at said station, means including means responsive to the operation of said switch to a predetermined position for completing a talking loop from said operator's 20 telephone to one of said private lines on a call from said central exchange routed over said trunk line to said one of said private lines, a second operator-controlled switch, and means including means responsive to the momentary operation of said second switch to a predetermined position for interrupting said talking loop and for completing a second talking loop from said operator's telephone to another of said private lines.
- 25 16. In a telephone system, a central exchange, a private exchange, a trunk line extending between said exchanges, private lines in said private exchange and accessible to said trunk line, at least a portion of said lines having private telephones individually associated therewith, an operator's station, an operator's telephone at said station, an operator-controlled switch at said station, means including means responsive to the momentary operation of said switch to a predetermined position for completing a talking loop from said operator's 30 telephone to one of said private lines on a call from said central exchange routed over said trunk line to said one of said private lines, a second operator-controlled switch, and means including means responsive to the momentary operation of said second switch to a predetermined position for interrupting said talking loop and for completing a second talking loop from said operator's telephone to another of said private lines.
- 35 17. In a telephone system, a central exchange, a private exchange, a trunk line extending between said exchanges, private lines in said private exchange and accessible to said trunk line, at least a portion of said lines having private telephones individually associated therewith, an operator's station, an operator's telephone at said station, an operator-controlled switch at said station, means including means responsive to the momentary operation of said switch to a predetermined position for completing a talking loop from said operator's 40 telephone to one of said private lines on a call from said central exchange routed over said trunk line to said one of said private lines, a second operator-controlled switch, and means including means responsive to the momentary operation of said second switch to a predetermined position for interrupting said talking loop and for completing a second talking loop from said operator's telephone to another of said private lines.
- 45 18. In a telephone system, a central exchange, a private exchange, a trunk line extending between said exchanges, private lines in said private exchange and accessible to said trunk line, at least a portion of said lines having private telephones individually associated therewith, an operator's station, an operator-controlled switch at said station having a normal position and being operable to at least one off-normal position, means including means responsive to the operation of said switch to a predetermined off-normal position for preparing a talking loop between one of said private telephones and said central exchange by way of said trunk line on a call to said one of said private lines routed over said trunk line, means responsive to the operation of said switch to its normal position for completing said loop, and means including means responsive to the operation of said switch to another off-normal position for releasing the established connection comprising said completed talking loop.
- 50 19. In a telephone system, a central exchange, a private exchange, a trunk line extending between said exchanges, private lines in said private exchange and accessible to said trunk line, at least a portion of said lines having private telephones associated therewith, an operator's station, operator-controlled switches at said station individually having a normal position and at least one off-normal position, means including means responsive to the operation of one of said switches to a predetermined off-normal position and to the momentary operation of another of said switches to a predetermined off-normal position for preparing a talking loop between one of said private telephones and said central exchange by way of said trunk line on a call to said one of said private lines routed over said trunk line, and means responsive to the operation of said one of said switches to its normal position for completing said loop.
- 55 20. In a telephone system, a central exchange, a private exchange, a trunk line extending between said exchanges, private lines in said private exchange and accessible to said trunk line, at least a portion of said lines having private telephones associated therewith, an operator's station, operator-controlled switches at said station individually having a normal position and at least one off-normal position, means including means responsive to the operation of one of said switches to a predetermined off-normal position and to the momentary operation of another of said switches to a predetermined off-normal position for preparing a talking loop between one of said private telephones and said central exchange by way of said trunk line on a call to said one of said private lines routed over said trunk line, means responsive to the operation of said one of said switches to its normal position for completing said loop, and means including means responsive to the operation of said one of said switches to a second off-normal position for releasing the established connection comprising said talking loop.
- 60 21. In a telephone system, a central exchange, a private exchange including an operator's station, a trunk line extending between said exchanges, private lines in said private exchange and accessible to said trunk line, an operator's telephone at said station and accessible to said trunk line, said operator's telephone including impulsing means, a normally uncompleted talk-

- ing loop including said trunk line and extending from said central exchange to said operator's telephone, means responsive to the initiation of a call over said trunk line from said central exchange to a line in said private exchange for partially completing said loop, a normally uncompleted talking loop extending from said operator's telephone to the called line and having associated therewith a local switch train 5 adapted to be responsive to impulses transmitted by said impulsive means, an operator-controlled switch having a normal position and at least two off-normal positions, means responsive to the operation of said switch to one off-normal position 10 for completing said first-named loop, for partially completing said second-named loop and for conditioning said local switch train to be responsive to impulses transmitted from said impulsive means, a second operator-controlled switch having a normal position and at least one off-normal position, means responsive to the momentary operation of said second switch to one off-normal position for interrupting said first loop and for connecting said operator's telephone to the uncompleted second loop, thereby 15 to permit impulses to be transmitted to cause said local switch train to operate and extend said second loop to said called line, means operable after the call to the called line is answered 20 and responsive to operation of said first-named switch to its normal position for completing a talking loop between said called line and said central exchange and for disconnecting said operator's telephone from said last-named loop, 25 and means including means responsive to the momentary operation of said first-named switch to a second off-normal position for restoring to normal the established connection comprising said last-named talking loop.
22. In a telephone system, a central exchange, a private exchange including an operator's station, a trunk line extending between said exchanges, private lines in said private exchange and accessible to said trunk line, an operator's telephone at said station and accessible to said trunk line, said operator's telephone including impulsive means, a normally uncompleted talking loop including said trunk line and extending from said central exchange to said operator's telephone, means responsive to the initiation of a call over said trunk line from said central exchange to a line in said private exchange for partially completing said loop, a normally uncompleted talking loop extending from said operator's telephone to the called line and having associated therewith a local switch train 30 adapted to be responsive to impulses transmitted by said impulsive means, an operator-controlled switch having a normal position and at least one off-normal position, means responsive to the momentary operation of said second switch to one off-normal position for interrupting said first loop and for connecting said operator's telephone to the uncompleted second loop, thereby to permit impulses to be transmitted to cause 35 said local switch train to operate and extend said second loop to said called line, means operable after the call to the called party line is answered and responsive to operation of said first-named switch to its normal position for completing a talking loop between said called line and said central exchange and for disconnecting said operator's telephone from said last-named loop, means responsive to the reoperation of said first-named switch to its said one off-normal position for connecting said operator's telephone to said last-named loop to monitor the call, and means including means responsive to the momentary operation of said first-named switch to a second off-normal position for restoring to normal the established connection comprising said last-named talking loop.
24. In a telephone system, a central exchange, a private exchange including an operator's station, a trunk line extending between said exchanges, private lines in said private exchange and accessible to said trunk line, an operator's telephone at said station and accessible to said trunk line, said operator's telephone including impulsive means, a normally uncompleted talking loop including said trunk line and extending from said central exchange to said operator's telephone, means responsive to the initiation of a call over said trunk line from said central exchange to a line in said private exchange for par-

able after the call to the called party line is answered and responsive to operation of said first-named switch to its normal position for completing a talking loop between said called line and said central exchange and for disconnecting said operator's telephone from said last-named loop, and means responsive to the reoperation of said first-named switch to its said one position for connecting said operator's telephone to said last-named loop to monitor the call.

23. In a telephone system, a central exchange, a private exchange including an operator's station, a trunk line extending between said exchanges, private lines in said private exchange and accessible to said trunk line, an operator's telephone at said station and accessible to said trunk line, said operator's telephone including impulsive means, a normally uncompleted talking loop including said trunk line and extending from said central exchange to said operator's telephone, means responsive to the initiation of a call over said trunk line from said central exchange to a line in said private exchange for partially completing said loop, a normally uncompleted talking loop extending from said operator's telephone to the called line and having associated therewith a local switch train adapted to be responsive to impulses transmitted by said impulsive means, an operator-controlled switch having a normal position and at least two off-normal positions, means responsive to the operation of said switch to one off-normal position for completing said first-named loop, for partially completing said second-named loop and for conditioning said local switch train to be responsive to impulses transmitted from said impulsive means, a second operator-controlled switch having a normal position and at least one off-normal position, means responsive to the momentary operation of said second switch to one off-normal position for interrupting said first loop and for connecting said operator's telephone to the uncompleted second loop, thereby to permit impulses to be transmitted to cause said local switch train to operate and extend said second loop to said called line, means operable after the call to the called party line is answered and responsive to operation of said first-named switch to its normal position for completing a talking loop between said called line and said central exchange and for disconnecting said operator's telephone from said last-named loop, means responsive to the reoperation of said first-named switch to its said one off-normal position for connecting said operator's telephone to said last-named loop to monitor the call, and means including means responsive to the momentary operation of said first-named switch to a second off-normal position for restoring to normal the established connection comprising said last-named talking loop.

25. In a telephone system, a central exchange, a private exchange including an operator's station, a trunk line extending between said exchanges, private lines in said private exchange and accessible to said trunk line, an operator's telephone at said station and accessible to said trunk line, said operator's telephone including impulsive means, a normally uncompleted talking loop including said trunk line and extending from said central exchange to said operator's telephone, means responsive to the initiation of a call over said trunk line from said central exchange to a line in said private exchange for par-

- 5 tially completing said loop, a normally uncom-
pleted talking loop extending from said operator's telephone to the called line and having associated therewith a local switch train adapted
5 to be responsive to impulses transmitted by said impulsive means, an operator-controlled switch having a normal position and at least one off-normal position, means responsive to the operation of said switch to one off-normal position
10 for completing said first-named loop, for partially completing said second-named loop and for conditioning said local switch train to be responsive to transmitted impulses from said impulsive means, a second operator-controlled
15 switch having a normal position and at least one off-normal position, means responsive to the momentary operation of said second switch to one off-normal position for interrupting said first loop and for connecting said operator's telephone to the uncompleted second loop, thereby to permit impulses to be transmitted to cause said local switch train to operate and extend said second loop to said called line, a third operator-controlled switch having a normal position and at least one off-normal position, and means including means responsive to the momentary operation of said third switch to one of its off-normal positions for interrupting the connection of said operator's telephone to said second loop, for releasing the established local switch train and for restoring said first-named talking loop.

20 25 30 35 40 45 50 55 60 65 70 75 80 85 90 95 100

25. In a telephone system, a central exchange, a private exchange including an operator's station, a trunk line extending between said exchanges, private lines in said private exchange and accessible to said trunk line, an operator's telephone at said station and accessible to said trunk line, said operator's telephone including impulsive means, a normally uncompleted talking loop including said trunk line and extending from said central exchange to said operator's telephone, means responsive to the initiation of a call over said trunk line from said central exchange to a line in said private exchange for partially completing said loop, a normally uncompleted talking loop extending from said operator's telephone to the called line and having associated therewith a local switch train adapted to be responsive to impulses transmitted by said impulsive means, an operator-controlled switch having a normal position and at least one off-normal position, means responsive to the operation of said switch to one off-normal position for completing said first-named loop, for partially completing said second-named loop and for conditioning said local switch train to be responsive to transmitted impulses from said impulsive means, a second operator-controlled switch having a normal position and at least one off-normal position, means responsive to the momentary operation of said second switch to one off-normal position for interrupting said first loop and for connecting said operator's telephone to the uncompleted second-named loop, thereby to permit impulses to be transmitted to cause said local switch train to operate and extend said second loop to said called line, a third operator-controlled switch having a normal position and at least two off-normal positions, means including means responsive to the momentary operation of said third switch to one of its off-normal positions for interrupting the connection of said operator's telephone to said second loop and for releasing the established local switch train, and means including means responsive to the operation of said third switch to a second off-normal position for releasing the established local switch train only.

35 40 45 50 55 60 65 70 75 80 85 90 95 100

27. In a telephone system a central exchange, a private exchange, a trunk line extending between said exchanges, private lines in said exchange, a link line adapted to be connected to said trunk line to render said private lines accessible to said trunk line, an operator's station, an operator's telephone at said station, and control means for establishing a talking loop from said central exchange over said trunk and link lines to any one of said private lines, said means including operator-controlled switches at said station and a plurality of relays, said switches individually having a normal position and at least one off-normal position, a first of said relays including contacts for connecting said operator's telephone to said trunk line, a second of said relays including contacts for connecting said operator's telephone to said link line, said first and second relays including energizing circuits controlled by said switches and so connected and arranged that said first relay is energized to close its contacts in response to the operation of one of said switches to one of its off-normal positions and said second relay is energized to close its contacts in response to the subsequent momentary operation of a second of said switches to one of its off-normal positions.

30 35 40 45 50 55 60 65 70 75 80 85 90 95 100

28. In a telephone system, a central exchange, a private exchange, a trunk line extending between said exchanges, private lines in said ex-

5 10 15 20 25 30 35 40 45 50 55 60 65 70 75 80 85 90 95 100

change, a link line adapted to be connected to said trunk line to render said private lines accessible to said trunk line, an operator's station, an operator's telephone at said station, and control means for establishing a talking loop from said central exchange over said trunk and link lines to any one of said private lines, said means including operator-controlled switches at said station and a plurality of relays, said switches individually having a normal position and at least one off-normal position, a first of said relays including contacts for connecting said operator's telephone to said trunk line, a second of said relays including contacts for connecting said operator's telephone to said link line, said first and second relays including energizing circuits controlled by said switches and so connected and arranged that said first relay is energized to close its contacts in response to the operation of one of said switches to one of its off-normal positions, said second relay is energized to close its contacts in response to the subsequent momentary operation of a second of said switches to one of its off-normal positions and both said first and second relays are de-energized in response to the subsequent operation of said one of said switches to its normal position.

29. In a telephone system, a central exchange, a private exchange, a trunk line extending between said exchanges, private lines in said exchange, a link line adapted to be connected to said trunk line to render said private lines accessible to said trunk line, an operator's station, an operator's telephone at said station, and control means for establishing a talking loop from said central exchange over said trunk and link lines to any one of said private lines, said means including operator-controlled switches at said station and a plurality of relays, said switches individually having a normal position and at least one off-normal position, a first of said relays including contacts for connecting said operator's telephone to said trunk line, a second of said relays including contacts for connecting said operator's telephone to said link line, said first and second relays including energizing circuits controlled by said switches and so connected and arranged that said first relay is energized to close its contacts in response to the operation of one of said switches to one of its off-normal positions, said second relay is energized to close its contacts in response to the subsequent momentary operation of a second of said switches to one of its off-normal positions and one of said first and second relays is permanently de-energized in response to the momentary operation of said other of said switches to a second off-normal position.

30. In a telephone system, a central exchange, a private exchange, a trunk line extending between said exchanges, private lines in said exchange, a link line adapted to be connected to said trunk line to render said private lines accessible to said trunk line, an operator's station, an operator's telephone at said station, and control means for establishing a talking loop from said central exchange over said trunk and link lines to any one of said private lines, said means including operator-controlled switches at said station and a plurality of relays, said switches individually having a normal position and at least one off-normal position, a first of said relays including contacts for connecting said operator's telephone to said trunk line, a second of said relays including contacts for connecting said operator's telephone to said link line, said first and second relays includ-

ing energizing circuits controlled by said switches and so connected and arranged that said first relay is energized to close its contacts in response to the operation of one of said switches to one of its off-normal positions and said second relay is energized to close its contacts in response to the subsequent momentary operation of a second of said switches to one of its off-normal positions, and means comprising a third one of said switches for interrupting the established connection of said operator's telephone to said link line.

31. In a telephone system, a central exchange, a private exchange, a trunk line extending between said exchanges, private lines in said private exchange accessible to said trunk line, at least a portion of said private lines having private telephones individually associated therewith, an operator's station, an operator-controlled answer switch at said station having a normal position and being operable to at least two different off-normal positions, another operator-controlled switch at said station having a normal position and being operable to at least one off-normal position, means responsive to the operation of said answer switch to one of said off-normal positions for preparing a talking loop between one of said private telephones and said central exchange by way of said trunk line on a call to said private exchange routed over said trunk line, means responsive to the operation of said answer switch to its normal position for completing said talking loop, means responsive to the operation of said other switch to a predetermined off-normal position for performing a predetermined service in connection with calls extending over said trunk line, and means responsive to the operation of said answer switch to a second of said off-normal positions for releasing the established connection comprising said talking loop.

32. In a telephone system, a central exchange, a private exchange, a trunk line extending between said exchanges, private lines in said private exchange accessible to said trunk line, at least a portion of said private lines having private telephones individually associated therewith, an operator's station, operator-controlled switches at said station individually having a normal position and being operable to at least one off-normal position, means including a relay responsive to the operation of one of said switches to a predetermined off-normal position for preparing a talking loop between one of said private telephones and said central exchange by way of said trunk line on a call to said private exchange routed over said trunk line, said relay having a holding circuit adapted to be completed in response to the operation of said relay, means responsive to the operation of said one of said switches to its normal position for completing said loop, means responsive to the operation of another of said switches to a predetermined off-normal position for performing a predetermined service in connection with calls extending over said trunk line, and means responsive to the operation of said one of said switches to a second off-normal position for interrupting the holding circuit of said relay to release the established connection comprising said talking loop.

33. In a telephone system, a central exchange, a private exchange, a trunk line extending between said exchanges, private lines in said private exchange and accessible to said trunk line, at least a portion of said private lines having private telephones individually associated therewith, an operator's station, an operator-controlled answer

- switch at said station having a normal position and being operable to at least two different off-normal positions, means including a relay responsive to the operation of said answer switch 5 to one of said off-normal positions for preparing a talking loop between one of said private telephones and said central exchange by way of said trunk line on a call to said private exchange routed over said trunk line, said relay having a 10 holding circuit adapted to be completed in response to the operation of said relay, means responsive to the operation of said answer switch to its normal position for completing said talking loop, and means responsive to the operation 15 of said answer switch to a second of said off-normal positions for interrupting the holding circuit of said relay to release the established connection comprising said talking loop.
34. In a telephone system, a central exchange, 20 a private exchange, a trunk line extending between said exchanges, private lines in said private exchange and accessible to said trunk line, at least a portion of said lines having private telephones individually associated therewith, an operator's 25 station, an operator's telephone at said station, an operator-controlled switch at said station having a normal position and being operable to at least two different off-normal positions, means responsive to the operation of said switch to one 30 of said off-normal positions for completing a talking loop from said operator's telephone to one of said private lines, means responsive to the operation of said switch to a second of said off-normal positions for interrupting said talking loop, and means responsive to the operation 35 of said switch to its normal position for completing a talking loop extending from said operator's telephone over said trunk line to said central exchange.
35. In a telephone system, a central exchange, 40 a private exchange, a trunk line extending between said exchanges, private lines in said private exchange and accessible to said trunk line, at least a portion of said lines having private telephones individually associated therewith, an operator's station, an operator's telephone at said station, an operator-controlled switch at said station, means responsive to the operation of said switch to a predetermined position for completing a talking loop from said operator's telephone to one of said private lines on a call from said central exchange routed over said trunk line to said one of said private lines a second operator-controlled switch at said station having a normal 45 position and being operable to at least one off-normal position, means responsive to the operation of said second switch to a predetermined off-normal position for interrupting said talking loop, and means responsive to the operation of 50 said second switch to its normal position for preparing a second talking loop from said operator's telephone to another of said private lines.
36. In a telephone system, a central exchange, 55 a private exchange, a trunk line extending between said exchanges, private lines in said private exchange and accessible to said trunk line, at least a portion of said lines having private telephones individually associated therewith, an operator's station, an operator's telephone at said station, said operator's telephone including impulsive means, a normally uncompleted talking loop extending from said operator's telephone to any one of the private lines in said private exchange and having associated therewith a local 60 switch train adapted to be responsive to impulses 65 transmitted from said impulsive means, an operator-controlled switch having a normal position and being operable to at least one off-normal position, means responsive to the operation of said switch to a predetermined off-normal position for connecting said operator's telephone to said talking loop, thereby to permit impulses to be transmitted to cause said local switch train to operate and extend said talking loop to a called private line in said private exchange, a second operator-controlled switch having a normal position and being operable to at least one off-normal position, and means responsive to the momentary operation of said second switch to a predetermined off-normal position for interrupting the connection of said operator's telephone to said talking loop, thereby to release said local switch train, and for then reconnecting said operator's telephone to said talking loop, thereby to permit impulses to be transmitted to cause said local switch train to operate and extend said talking loop to a called private line in said private exchange.
37. In a telephone system, a central exchange, 70 a private exchange, a trunk line extending between said exchanges, private lines in said private exchange and accessible to said trunk line, at least a portion of said private lines having private telephones individually associated therewith, an operator's station, an operator-controlled answer switch at said station having a normal position and being operable to at least two different off-normal positions, means including a relay responsive to the operation of said answer switch to one of said off-normal positions for preparing a talking loop between one of said private telephones and said central exchange by way of said trunk line on a call to said private exchange routed over said trunk line, said relay having a holding circuit adapted to be completed in response to the operation of said relay, means responsive to the operation of said answer switch to its normal position for completing said talking loop, and means responsive to the operation of said answer switch to a second of said off-normal positions for interrupting the holding circuit of said relay to release the established connection comprising said talking loop.
38. In a telephone system, a central exchange, 75 a private exchange, a trunk line extending between said exchanges, private lines in said private exchange and accessible to said trunk line, at least a portion of said private lines having private telephones associated therewith, an operator's station, operator-controlled switches at said station, each of said switches having a normal position and at least one off-normal position, means responsive to the operation of one of said switches to a predetermined off-normal position for preparing a portion of a talking loop between one of said private telephones and said central exchange by way of said trunk line on a call to said one of said private lines routed over said trunk line, means responsive to the momentary operation of another of said switches to a predetermined off-normal position for preparing another portion of said talking loop, and means responsive to the operation of said one of said switches to its normal position for completing said talking loop.
39. In a telephone system, a central exchange, 80 a private exchange, a trunk line extending between said exchanges, private lines in said private exchange and accessible to said trunk line, at least a portion of said private lines having

private telephones associated therewith, an operator's station, an operator-controlled answer switch at said station having a normal position and being operable to at least two off-normal positions, another operator-controlled switch at said station having a normal position and being operable to at least one off-normal position, means responsive to the operation of said answer switch to one of said off-normal positions for preparing a portion of a talking loop between one of said private telephones and said central exchange, means responsive to the momentary operation of said other switch to a predetermined off-normal position for preparing another portion of said talking loop, means responsive to the operation of said answer switch to its normal position for completing said talking loop, and means responsive to the operation of said answer switch to a second of said off-normal positions for releasing the established connection comprising said talking loop.

40. In a telephone system, a central exchange, a private exchange including an operator's station, a trunk line extending between said exchanges, private lines in said private exchange and accessible to said trunk line, an operator's telephone at said station and accessible to said trunk line, said operator's telephone including impulsive means, a normally uncompleted talking loop including said trunk line and extending from said central exchange to said operator's telephone, means responsive to the initiation of a call over said trunk line from said central exchange to a line in said private exchange for partially completing said loop, a normally uncompleted talking loop extending from said operator's telephone to the called line and having associated therewith a local switch train adapted to be responsive to impulses transmitted from said impulsive means, an operator-controlled answer switch having a normal position and being operable to at least two different off-normal positions, means responsive to the operation of said answer switch to one of said off-normal positions for completing said first-named talking loop and for conditioning said local switch train to be responsive to impulses transmitted from said impulsive means, means including a relay operated in response to the operation of said last-named means for partially completing said second-named talking loop, said relay having a holding circuit adapted to be completed in response to the operation of said relay, a second operator-controlled switch having a normal position and being operable to at least one off-normal position, means including a second relay responsive to the operation of said second switch to a predetermined off-normal position for interrupting said first-named talking loop and for connecting said operator's telephone to said uncompleted second-named talking loop, thereby to permit impulses to be transmitted to cause said local switch train to operate and extend said second-named talking loop to said called line, said second relay having a holding circuit adapted to be completed in response to the operation of said second relay, means operative after the call to the called line is answered and responsive to the operation of said answer switch to its normal position for interrupting the holding circuit of said second relay, thereby to complete a talking loop between said called line and said central exchange and for disconnecting said operator's telephone from said second-named talking loop, and means responsive to the reoperation of said answer switch to said predetermined off-normal position for connecting said operator's telephone to said third-named talking loop to monitor the call.

41. In a telephone system, a central exchange, a private exchange including an operator's station, a trunk line extending between said exchanges, private lines in said private exchange and accessible to said trunk line, an operator's telephone at said station and accessible to said trunk line, said operator's telephone including impulsive means, a normally uncompleted talking loop including said trunk line and extending from said central exchange to said operator's telephone, means responsive to the initiation of a call over said trunk line from said central exchange to a line in said private exchange for partially completing said loop, a normally uncompleted talking loop extending from said operator's telephone to the called line and having associated therewith a local switch train adapted to be responsive to impulses transmitted by said impulsive means, an operator-controlled answer switch having a normal position and being operable to at least one off-normal position, means responsive to the operation of said answer switch to a predetermined off-normal position for completing said first-named talking loop, for partially completing said second-named talking loop and for conditioning said local switch train to be responsive to impulses transmitted from said impulsive means, a second operator-controlled switch having a normal position and being operable to at least one off-normal position, means including a relay responsive to the operation of said second switch to a predetermined off-normal position for interrupting said first-named talking loop and for connecting said operator's telephone to the uncompleted second-named talking loop, thereby to permit impulses to be transmitted to cause said local switch train to be operated and extend said second-named talking loop to said called line, said relay having a holding circuit adapted to be completed in response to the operation of said relay, means operative after the call to the called line is answered and responsive to the operation of said answer switch to its normal position for interrupting the holding circuit of said relay, thereby to complete a talking loop between said called line and said central exchange and for disconnecting said operator's telephone from said second-named talking loop, and means responsive to the reoperation of said answer switch to said predetermined off-normal position for connecting said operator's telephone to said third-named talking loop to monitor the call.

42. In a telephone system, a central exchange, a private exchange including an operator's station, a trunk line extending between said exchanges, private lines in said private exchange and accessible to said trunk line, an operator's telephone at said station and accessible to said trunk line, said operator's telephone including impulsive means, a normally uncompleted talking loop including said trunk line and extending from said central exchange to said operator's telephone, means responsive to the initiation of a call over said trunk line from said central exchange to a line in said private exchange for partially completing said loop, a normally uncompleted talking loop extending from said operator's telephone to the called line and having associated therewith a local switch train adapted to be responsive to impulses transmitted from said impulsive means, an operator-controlled switch having a normal position and at least one off-normal position, means responsive to the operation of said operator-controlled switch to a second off-normal position for interrupting the holding circuit of said first-named relay to release the established connection comprising said last-named talking loop.

off-normal position, means responsive to the operation of said switch to one off-normal position for completing said first-named loop, for partially completing said second-named loop and for conditioning said local switch train to be responsive to impulses transmitted from said impulsive means, a second operator-controlled switch having a normal position and at least one off-normal position, means responsive to momentary operation of said second switch to one off-normal position for interrupting said first loop and for connecting said operator's telephone to the uncompleted second loop, thereby to permit impulses to be transmitted to cause said local switch train to operate and extend said second loop to said called line, a third operator-controlled switch having a normal position and at least one off-normal position, and means responsive to momentary operation of said third switch to one of its off-normal positions for interrupting the connection of said operator's telephone to said second loop, for releasing the established local switch train and for then reconditioning said local switch train to be responsive again to the transmitted impulses from said impulsive means.

43. In a telephone system, an operator's station including apparatus operable to set up connections between a trunk line and any one of a plurality of private lines, said apparatus comprising, in combination, a link-line, an operator's telephone, a plurality of operator-controlled switches, and a plurality of relays, said switches individually having a normal position and at least one off-normal position, a first of said relays including contacts for connecting said operator's telephone to said trunk line, a second of said relays including contacts for connecting said operator's telephone to said link line, said first and second relays including energizing circuits controlled by said switches and so connected and arranged that said first relay is energized to close its contacts in response to the operation of one of said switches to one of its off-normal positions and said second relay is energized to close its contacts in response to the subsequent momentary operation of a second of said switches to one of its off-normal positions.

44. In a telephone system, a central exchange, a private exchange, a trunk line extending between said exchanges, private lines in said private exchange, a link line adapted to be connected to said trunk line to render said private lines accessible to said trunk line, an operator's station, an operator's telephone at said station, an oper-

ator-controlled answer switch at said station having a normal position and being operable to at least one off-normal position, a second operator-controlled switch at said station having a normal position and being operable to at least one off-normal position, means including a first relay for connecting said operator's telephone to said trunk line, a circuit for energizing said first relay, means including a second relay for connecting said operator's telephone to said link line, a circuit for energizing said second relay, means responsive to the operation of said answer switch to a predetermined off-normal position for completing the circuit for energizing said first relay, means responsive to the subsequent operation of said second switch to a predetermined off-normal position for completing the circuit for energizing said second relay, and means responsive to the subsequent operation of said answer switch to its normal position for interrupting the circuits for energizing both of said relays.

45. In a telephone system, a central exchange, a private exchange, a trunk line extending between said exchanges, private lines in said private exchange, a link line adapted to be connected to said trunk line to render said private lines accessible to said trunk line, an operator's station, an operator's telephone at said station, an operator-controlled answer switch at said station having a normal position and being operable to at least one off-normal position, a second operator-controlled switch at said station having a normal position and being operable to at least one off-normal position, means including a first relay for connecting said operator's telephone to said trunk line, an operating circuit for said first relay, means including a second relay for connecting said operator's telephone to said link line, said second relay having an operating circuit and a holding circuit, means responsive to the operation of said answer switch to a predetermined off-normal position for completing the operating circuit of said first relay, means responsive to the subsequent momentary operation of said second switch to a predetermined off-normal position for completing the operating circuit of said second relay, the holding circuit of said second relay being arranged to be completed upon the operation of said second relay, and means responsive to the subsequent operation of said answer switch to its normal position for interrupting the operating circuit of said first relay and for interrupting the holding circuit of said second relay.
